UNITED STATES PATENT OFFICE.

DAVID L. LINDQUIST, OF HARTSDALE, NEW YORK; EDWARD L. DUNN, OF EAST ORANGE, NEW JERSEY; AND DAVID C. LARSON, OF YONKERS, NEW YORK, ASSIGNEES TO OTIS ELEVATOR COMPANY, OF JERSEY CITY, NEW JERSEY, A CORPORATION OF NEW JERSEY.

ELEVATOR SYSTEM.

Original application filed May 21, 1925, Serial No 31,953. Divided and this application filed November 7, 1925. Serial No. 67,589.

This application is a division of application Serial No. 31,953, filed May 21, 1925.

The invention relates to electric elevator systems, particularly systems of the automatic push button type.

One feature of the invention is to cause a push button controlled elevator car to stop automatically to pick up prospective passengers desired to be carried in the direction in which 10 the car is traveling.

Another feature is to have one car of a bank of elevators bear the brunt of the service when the demand is light and to cause other cars to go into operation automatically 15 as the demand for service increases.

A third feature involves the stopping of only one car at a floor in response to the pushing of a button by a prospective passenger when several cars are in operation.

20 A fourth feature resides in causing at least one car to continue in operation until response is had to all buttons pushed.

A fifth feature is to cause the cars to return to selected floors after response is had 25 to all push buttons operated.

Other features and advantages will become apparent from the following description, taken in connection with the accompanying drawings wherein one embodiment of the invention is illustrated and in which:

Figure 1 is a simplified schematic representation of two elevators, as illustrative of a group of elevators in a bank;

Figure 2 is a front elevation of the "director switch" with the cover plate removed;

Figure 3 is a view, partly in elevation and partly in section, taken along line 3—3 of Figure 2;

Figure 4 is a view in horizontal section, 40 with parts broken away, taken along the line 4—4 of Figure 2;

Figure 5 is a front elevation of the "director switch" reversing mechanism;

Figure 6 is a plan view of the same;

Figure 7 is a detail, partly in section, of a cam operated switch;

Figure 8 is a detail in section, taken along line 8—8 of Figure 5, of a portion of the connecting rod of the "director switch" reversing mechanism;

Figure 9 is a front elevation, with parts broken away, of the selector machine;

Figure 10 is a side elevation of the same, also with parts broken away;

Figure 11 is a plan view of the same, also 55 with parts broken away;

Figure 12 is a detail in plan of a brush;

Figure 13 is a section, with parts in elevation, taken along line 13—13 of Figure 12;

Figure 14 is a fragmental view, taken along 60 line 14—14, of Figure 11, of a brush and contact in engagement;

Figure 15 is a fragmental view of the arrangement of the pawl magnet limit switches and operating cam;

Figure 16 is a front elevation of a floor switch;

Figure 17 is a side elevation of the same;

Figure 18 is a diagrammatic representation of the arrangement of the switches mounted 70 on the "master" panel;

Figure 19 is a view in section, taken along the line 19—19 of Figure 20, of the time switch;

Figure 20 is a view in section taken along 75 line 20—20 of Figure 19, with the motor omitted;

Figure 21 is a view in section, taken along line 21—21 of Figure 19;

Figure 22 is a diagrammatic representation of the control panel showing particularly 80 the relation of the coils and contacts of various control switches;

Figure 23 is a simplified diagram of the power and control system used for each elevator; and

Figure 24 is a simplified diagram, extended from Figure 23, of the push button control system for two elevators, as illustrative of a group.

For a general understanding of the invention, reference may be had to Figure 1 wherein various parts of the system are indicated by legend. Referring particularly to the left half of the figure wherein the parts for one elevator, hereinafter to be known as Elevator No. 1, are represented, the car is driven by the elevator motor. This motor receives its power from the generator of a motor-generator set, the voltage of the generator 95 100

being controlled by various electromagnetic switches mounted on the control panel. An exciter, for supplying current to the generator and elevator motor fields and certain of the control circuits, is driven by the motor of the motor generator-set.

The direction of travel of the car is determined by the "director switch". "Director switch" hatchway cams are arranged at the 10 terminal floors for moving the "director switch" into "neutral" position to stop the car. The "director switch" motor moves the "director switch" from "neutral" into reversed position. The car is stopped at the intermediate floors by the selector machine. The door lock cam motor is provided for controlling the locking and unlocking of the well doors. A leveling switch and leveling cams may be provided for causing the car to be 20 brought to the landing in the event that an exact stop has not been made.

A "director switch" motor switch is provided in the car for reversing the direction of travel of the car when occasion demands 25 it. A safety switch also is provided in the car for stopping the car in the event of an emergency.

The other elevators in a group, as indicated by Elevator No. 2, are arranged in an 30 identical manner. Up and down push buttons, common to all the elevators, are arranged at the intermediate floors. An up push button is arranged at the bottom floor and a down push button at the top floor, these 35 buttons also being common to all the elevators. These push buttons, to be known as hall buttons, are for causing the cars to start in accordance with a predetermined arrangement and, if started, for causing the selector 40 machines to stop their respective cars at the landings.

Each elevator car is provided with an independent set of push buttons, one button being provided for each floor. These push 45 buttons, to be known as car buttons, are for causing the respective cars to start and, if started, for causing the selector machines to stop their respective cars at the landings. The car buttons for each car may also affect 50 the operation of the other cars in accordance with a predetermined arrangement.

The hall buttons and car buttons are preferably arranged to act through floor switches mounted on the "master" panel.

55 The system will be described as applied to a ten floor installation. It is to be understood, however, that the system may be arranged for any number of floors, ten being chosen merely for purposes of description.

60 The "director switch", selector machine, floor switches and a time switch will be described for Elevator No. 1, it being understood that these devices are identical for all the elevators of a group.

65 Referring to Figures 2, 3 and 4, the details

of the preferred form of "director switch" will be described. This switch, designated as a whole by numeral 30, is enclosed in a suitable casing 31 and casing cover plate 32. The casing is provided with brackets 33 and 70 bosses 34 arranged for mounting the switch on the elevator car frame 129, as illustrated in Figures 5 and 6. Within the casing and secured, as by screws, to a plurality of bosses 35 extending from the casing base 36 is an 75 annular contact support 37. This support has two arcuate slots 38 and 40 in which a plurality of insulating contact bases 41 are adjustably mounted. Suitable spring contacts are secured to these bases, contacts 43 80 and 42 controlling the circuits for the actuating oils of the up and down direction switches respectively, and contacts 44, 45, 46 and 47 controlling the circuits for the actuating coils of the accelerating switches. Two feed contacts 48 and 50, similar in construction to the control contacts, are mounted on a support 51 of insulating material. This support, along with an intervening insulating strip 52, is secured to an arcuate boss 53 formed on the 85 contact support 37.

Segment 54, for bridging the above mentioned contacts, comprises an arcuate channel member, formed of an outer flanged portion 55, inner flanged portion 56 and connecting web 57, and a supporting arm 58. The outer flange 55 is arranged for bridging either set of control contacts 42, 44 and 45 or 43, 46 and 47, while the inner flange 56 is arranged to engage either feed contact 48 or 50. It 100 will be observed that a circuit may thus be completed from either feed contact to the corresponding set of control contacts. Oil wipers 60 and 61 are mounted on insulating support 51 to engage the contact surfaces of 105 flanges 55 and 56 respectively. The supporting arm 58 is mounted on shaft 62 between two insulating plates 63 and 64. A projection 65 on plate 64 extends through an aperture 66 in supporting arm 58 into a 110 recess formed in plate 63. Shaft 62 extends through an inner aperture 67 formed in projection 65 and through plate 63. Two other projections 68 are formed on plate 64 and are disposed diametrically opposite the projection 65. These latter projections are similarly arranged to extend through apertures in supporting arm 58 into recesses in plate 63. A sleeve 70, arranged on shaft 62 is formed with a flange 71 adjacent to plate 63. Flange 115 71, plate 63 and projections 68 are apertured to receive studs 72. Nuts 73 on the threaded ends of these studs, clamp the supporting arm 58, plates 63 and 64 and a separating washer 74 against the flange 71. It will be observed 120 that with this arrangement the segment 54 is completely insulated from the flange 71 and shaft 62. A pinion 75 is arranged on shaft 62 in abutting relation with the end of sleeve 70. The pinion, sleeve and segment 125 130

are held in assembled relation against a shoulder 76, formed on shaft 62, by means of a nut 77 and locking pin 79. A key 80, mounted in a keyway in shaft 62, forms a driving connection between pinion 75 and sleeve 70, while the flange 71 and studs 72 form an operating connection between sleeve 70 and segment 54.

Pinion 75 is driven by means of a segmental gear 81. This gear is mounted on the 10 inner end of a driving shaft 82, being secured thereto as by means of a through bolt 83. Shaft 82 extends through its supporting bearing 84 to the outside of the casing. An operating arm 85 is mounted on the outer end 15 of shaft 82, being similarly secured thereto as by means of another through bolt 83. A roller 86, for engaging the "director switch" hatchway cams 87 (see Figure 1), is mounted on the free end of operating arm 85. Another 20 operating arm 88 and a cam supporting segment 90 are mounted on the shaft 82 between the operating arm 85 and the bearing 84. One end of a connecting rod 91 is pivotally secured, as by pin 92, to the free end of 25 operating arm 88. The other end of connecting rod 91 is secured to the "director switch" reversing mechanism as will be described later.

Shaft 62 also extends through its supporting bearing 93 to the outside of the casing, the other end of the shaft being formed with a positioning flange 94. Within the casing, two friction plates 95 and 96 are mounted on sleeve 70, the sleeve being square in cross section to form a driving connection. These friction plates cooperate with a stationary annular disc 97 to maintain the "director switch" in the position into which it has been moved. The annular disc 97 is provided with 40 apertured lugs 98. Projections 100, extending from base 36, fit into the apertures of the lugs 98 to hold disc 97 against turning. Friction plate 95, arranged on one side of the disc 97, abuts against pinion 75. Friction plate 96 is forced against the other side of the disc, and the disc against friction plate 95, by 45 means of springs 101 mounted on the studs 72. These studs extend into apertures 102 formed in friction plate 96.

50 Adjustable abutment screws 103, mounted in the sides of the casing 31, determine the limits of movement of the segmental gear 81. These screws form stops to prevent the disengagement of the contacts and bridging segment 54 by extreme movement of the segmental gear in either direction. A suitable opening 104 is provided in the casing 31 for the various conductors leading to and from the "director switch" contacts.

55 A pair of switches 105 and 106, identical in construction, are secured to the outside of the casing base 36 as indicated most clearly in Figure 5. Each switch is provided with an operating roller 107 disposed in the path 60 of movement of cams 108 mounted on segment

90. Each cam 108 is adjustably secured to the segment as by means of screws 109.

Referring to Figure 7, the details of one of the switches 105, 106 will be described. The contact holder 110 for the stationary contact 111 is mounted on a frame 112, of insulating material. The frame 112, comprises two side members 113 (one of the sides not being shown in order that the switch may be more clearly illustrated) and a connecting web 114. The stem 115 of the contact holder extends through the web 114, its extended end being provided with nuts 116 for securing the holder to the frame and for securing the terminal clip of a conductor. The movable contact 117 for engaging the stationary contact is carried by an operating arm 118. The arm 118 is pivotally mounted, as by a pin 120, on a bracket 121. Bracket 121 is provided with a stud 122 which extends through the web 114 and which is provided with nuts 116 for securing the bracket to the frame 102 and for securing the terminal clip of a conductor. Beyond its pivot point the operating arm 118 is formed with two lugs 123 between which 95 extends a pin 124 for pivotally supporting the roller 107. A spring 125, tending to bias the switch to closed position, extends between spring seats, one seat being formed on the extended portion of the operating arm 118 and one on the bracket 121. Apertures 126 are provided for receiving the mounting screws. Thus upon a cam 108 moving under the roller 107, the operating arm 118 is rocked counter-clockwise about its pivot causing the separation of the contacts 111 and 117 and the compression of spring 125. As the cam moves off the roller the spring 125 rocks the operating arm clockwise causing the reengagement of the contacts.

Referring to Figures 5 and 6, the preferred form of "director switch" reversing mechanism will be described. The "director switch" motor 127 is mounted on a support 128 secured to the car frame 129. One end of the 100 motor shaft has secured thereto a pinion 130. The motor operates a segmental gear 131 through pinion 130, the segmental gear being pivotally supported by a bracket 132 depending from support 128. The segmental gear 131 in turn operates the "director switch" through the connecting rod 91 and arm 88. The connecting rod 91 comprises an end piece 133, pivotally mounted on a pin 134 provided on the segmental gear 131, a rod 135, buffer spring 136, and buffer yoke 137. As 110 illustrated in Figure 8, a threaded bushing 138 is adjustably mounted in one end of yoke 137, a nut 140 being provided for locking the bushing in adjusted position. The rod 135 extends slidably through the bushing, the free end of the rod being reduced in diameter to form a shoulder. A piston 141 is secured to the extreme end of rod 135 and is arranged to 120 slide in the cylinder 142 formed in the yoke 130 125

137. The buffer spring 136 is disposed in an opening 143 provided in the yoke 137 and extends between washers abutting against the shoulder on rod 135 and the shoulder formed by the piston 141. The purpose of this arrangement is to absorb any shocks caused by sudden movement of either the "director switch" motor or operating arm 88 as will be seen from later description.

140 It will be noted, upon reference to Figure 1, that the bottom floor hatchway cam 87 extends up the hatchway so as to engage the "director switch" roller 86 with the car quite a distance from the terminal landing, the distance depending upon the particular installation. During downward movement of the car, the initial engagement of the cam and roller causes the "director switch" to be moved into a position to cause a reduction in the speed of the car. From this point of engagement, the cam 87 slopes gradually to the left down to the point where it moves the "director switch" to "neutral" position. From this latter point, the cam is vertical, the "director switch" being moved into reversed position by the "director switch" motor 127 as will be described later. The cam at the top floor is identical in construction but reversed so as to move the "director switch" from up position 145 into "neutral" position.

150 In operation, assume that the "director switch" is in down position, as indicated by roller 86 and operating arm 85 in broken lines, Figures 2 and 5, and in full lines in Figure 6, it being noted that the rear view of the "director switch" is illustrated in Figure 5. In this position, flange 55 bridges control contacts 42, 44 and 45 and flange 56 engages feed contact 48. As the car approaches the bottom floor, roller 86, engaging cam 87, is carried gradually to the left. The initial movement of arm 88, due to the engagement of the cam and roller, causes the yoke 137 to slide to the left on the rod 135 and piston 141, the portion of the yoke forming the right end of opening 143 acting through the washer to compress the spring 136 against the shoulder formed on rod 135. By employing the initial force to compress the spring in this manner, the inertia of the parts of the reversing mechanism is gradually overcome and the movement of arm 88 is transmitted to the "director switch" motor through segmental gear 131 without strain. As a result of the initial movement of roller arm 85, the segmental gear 81 rotates segment 54 in a counter-clockwise direction. In this manner the circuits controlled by contacts 45, 44 and 42 are broken in the order of the contacts named. As the roller arm is moved into "neutral" position flange 56 moves off feed contact 48. Motor 127 is energized, in a manner to be described later, to move the "director switch" from "neutral" into up position. The initial movement of the segmen-

tal gear 131 caused by the rotation of motor 127 causes the rod 135 and piston 141 to slide to the left in the yoke 137, the piston acting through the washer to compress spring 136 against the inner end of the bushing 138. In this manner the movement of the motor 127 is similarly transmitted to the "director switch" without strain. Thus as the "director switch" is moved into up position, similarly indicated by broken lines in Figures 2 and 5, segment 54 is caused to engage contacts 50, 43, 46 and 47, preparing the control circuits for up operations of the car. The friction plates 95 and 96 and disc 97 permit the movement of the segment 54 but, after the reversing operation, hold it in reversed position. Under normal operation, therefore, the segment 54 remains in up position until similarly but oppositely moved by the hatchway cam 87 and motor 127 at the top floor into down position. Again, the friction plates and disc maintain the switch in this last moved position. Thus the "director switch" is normally in one of its on positions.

155 The "director switch" motor is deenergized, upon the completion of each reversal of the "director switch", by the opening of either switch 105 or switch 106, depending on the position into which the "director switch" is moved. As previously explained, these switches are opened by the engagement of their operating rollers 107 and the cams 108. With the "director switch" in one of its reversed positions, the corresponding switch 105 or 106 is maintained open by its cam 108, as illustrated for switch 105 in Figure 5. As will be described in conjunction with the description of operation of the system as a whole, means are provided for causing the motor 127 to reverse the "director switch" at any point at will. It is to be noted, however, that the "director switch" cannot be reversed into its former position at the terminal landings due to the fact that the vertically extending portions of the hatchway cams 87 act as stops. The selector machine may be arranged to cause the motor 127 to reverse the "director switch" at any floor as will be described later.

160 Reference may now be had to Figures 9 to 11 inclusive which illustrate the various details of a preferred form of selector machine. This machine, designated as a whole by the numeral 145, comprises a frame formed by a base member 146, four standards 147, 148, 150 and 151 and a top member 152. The standards are secured in sockets formed in bosses 153 on base member 146 and sockets formed in bosses 154 on top member 152. Eight switches are provided on the machine, namely, the up "selector" first slow-down switch 155, second slow-down switch 156, stop switch 157 and door lock control switch 158, and the down "selector" first slow-down switch 160, second slow-down switch 130

161, stop switch 162 and door lock control switch 163.

Referring particularly to Figure 9, the up "selector" switches 155, 156, 157 and 158 are mounted on a bracket 164 secured to top member 152 as by bolts. Each switch comprises a stationary contact 165 and a movable contact 166. These contacts may be of any well known construction. The stationary contacts are mounted on an insulating contact plate 167 supported by the bracket 164. Each stationary contact is provided with nuts 168 for securing the contact to the contact plate and for connecting the respective switch in the system. Each movable contact is mounted in an arm 170 of a contact lever, lever 171 being for the first slow-down switch, lever 172 being for the second slow-down switch, lever 173 being for the stop switch and lever 174 being for the door lock control switch. With the switches in closed positions, each movable contact is pressed into engagement with its corresponding stationary contact by means of a spring 175. Each movable contact is insulated from its contact lever and is connected, as by a flexible conductor 176, to a corresponding binding post 177 on contact plate 167. All the contact levers are pivotally mounted on a pin 178 supported by arms 180 depending from bracket 164. The other arm 181 of each lever is enlarged to form a weight. Each weight acts as a bias tending to move its respective switch to closed position. Also pivotally mounted on pin 178, preferably between contact levers 172 and 173, is a bell crank lever 182. The vertical arm 183 of the bell crank lever is T shaped, the cross member 184 of the T being provided with lugs 189 which extend into the paths of the contact levers. Abutment screws 185, 186, 187 and 188, adjustably mounted in the arms 170 of contact levers 171, 172, 173 and 174 respectively, are arranged for engagement by the lugs 189 during the operation of the switches. The abutment screws are preferably adjusted so that first screw 185, then screw 186 and then screws 187 and 188 are engaged by the corresponding lugs 189 on the cross member 184 to cause the consecutive opening in the order named of the first slow-down switch 155, the second slow-down switch 156 and then simultaneously the stop switch 157 and door lock control switch 158 respectively. It is to be understood that refinements of adjustments may be made to suit the operating conditions of the particular installation. A socket 190 is pivotally mounted on the horizontal arm 191 of bell crank lever 182. A vertical tube 192 is secured in socket 190, as by means of a pin 193. This tube extends into and is similarly secured in another socket 194. The socket 194 is pivotally mounted on the horizontal arm 195 of a bell crank lever 196. Bell crank

lever 196 is pivotally mounted between supports 197 formed on base member 146.

The down "selector" switches 160, 161, 162 and 163 are identical in construction with the corresponding up "selector" switches 155, 156, 157 and 158, above described, and are similarly mounted on bracket 198. The mechanical construction of the closing mechanism is similar. The horizontal arm 200 of the top bell crank lever 201 and the horizontal arm 202 of the bottom bell crank lever 203, however, extend to the left instead of to the right as do the corresponding arms of bell crank levers 182 and 196. Thus to open switches 155, 156, 157 and 158, tube 192 must move in the up direction as indicated, while to open switches 160, 161, 162 and 163, tube 204, extending between levers 201 and 203, must move in the down direction. The depending arms 205 of the bottom bell crank levers 196 and 203 are joined by means of a cross rod 206. With the cross rod connection, tube 192 must be pulled in the up direction in order to effect the downward movement of tube 204 and, conversely, tube 204 must be pulled in the up direction in order to effect the downward movement of tube 192. Thus the weight of one tube is counterbalanced by the weight of the other. An adjustable screw stop 207 extends through a connecting web 208 for supports 197 into abutting relation with end piece 210 provided on cross rod 206. A weight 211, provided in the lower end of tube 192, serves to unbalance tubes 192 and 204 and acts as a bias tending to maintain the switch opening mechanism in normal position, i. e., the position in which end piece 210 engages screw stop 207. The screw 207 is so adjusted that, with the switch opening mechanism in normal position, the "selector" switches will be free to return to closed positions. A preferred form of mechanism for causing the operation of the switches will now be described.

Referring to Figure 1, the selector machine is driven preferably by means of two steel tapes 212 and 213 attached to the car. Tape 212 extends from the top of the car to an overhead sheave 214 around which it is wound in a manner similar to the winding of a measuring tape. The other tape 213 extends from the bottom of the car around a tension sheave 215 and then up to a second overhead sheave 216 upon which it is similarly but oppositely wound. These overhead sheaves are keyed to the operating shaft 217 of the automatic floor stop machine, one tape winding up as the other unwinds in the driving operation. This silent drive is as positive as a sprocket chain and is unaffected by sliding or stretching ropes.

Referring again to Figure 9, the base member 146 is formed with a centrally disposed pedestal 218. This pedestal and the boss 153,

for standard 147, are arranged to provide bearings 220 and 221 respectively for the shaft 217. The pedestal 218 is further arranged to receive a vertical bearing 222 and 5 to support a ball thrust bearing 223 for screw 224. This screw extends vertically into a bearing 225 formed in the top member 152. A beveled gear 226 is secured, as by pin 227, to the lower end of screw 224. Another 10 beveled gear 228, engaging gear 226 in a driving relation, is secured, as by pin 230, to operating shaft 217. Operative engagement between the beveled gears is maintained by positioning collars 231 secured on shaft 217. 15 A crosshead, comprising a forked end 232, a nut 233 and frame 234 extending therebetween, is arranged to be driven by screw 224. The forked end 232 engages a vertically extending bar 235 to form a guide for the crosshead. Bar 235 is secured to lugs 236 and 237 formed on base member 146 and top member 152 respectively. A pawl magnet frame 238 is carried by the crosshead nut 233, being secured thereto as by bolts. Frame 238 is 20 arranged to receive the pawl magnet 240. The pawl magnet comprises a coil 241 and central core 242. Non-magnetic plates 243, positioned at each end of the pawl magnet, are secured to the frame 238 as by means of 25 through bolts 244. These plates form a mounting for the pawl magnet, being provided with recesses 245 into which the core 242 extends. The pawl magnet armatures 246 and 247 are pivotally mounted, as by 30 means of pins 248, on arms 250 extending outwardly in opposite directions from the top and bottom of frame 238. The non-magnetic plates 243 further serve as spacing members to prevent armatures 246 and 247 from being 35 held in by residual magnetism. Armature 246 extends inwardly from its pivot point to form an arm 251. The end of arm 251 is bifurcated to slidably engage a sleeve 252, the sleeve being mounted on a pin 253 secured in frame 238. A spring 254 is arranged on pin 253 above the sleeve in such manner as to be compressed by arm 251 when the armature is drawn in by pawl magnet 240. Between its end and pivot point, the arm is 40 enlarged to form a weight 255. Spring 254 and weight 255 act to move the armature into unattracted position when the pawl magnet coil 241 is deenergized, the spring acting to give rapid initial movement. An adjusting 45 screw 256, provided in arm 251, engages frame arm 250 to determine the amount of outward movement of the armature. Armature 247 is similarly arranged with an arm, slot, pin, spring and adjusting screw but is reversed. Thus its weight 257, in order to 50 function properly, extends outwardly from the pivot point. Pawls 258 and 260 are secured, as by screws, to armatures 246 and 247 respectively, pawl 260 being reversed to 55 correspond with its armature. These pawls,

with armatures 246 and 247 in unattracted position, are arranged to engage stopping collars 261 provided on tubes 192 and 204. Each tube is provided with nine of these stopping collars, tube 192 with collars for the 7" second to the tenth floors inclusive for operative engagement by pawl 260 to stop in the up direction and tube 204 with collars for the ninth to the first floors inclusive for operative engagement by pawl 258 to stop in the down direction. Each collar 261 may be formed with a U bolt 262 and clamping plate 263 so as to be readily adjustable. 75

The "selector" first slow-down switches 155 and 160 are arranged in the circuits for the actuating coils of second and third accelerating switches. The "selector" second slow-down switches 156 and 161 are arranged in the circuits for the actuating coil of the first accelerating switch. The "selector" stop switches 157 and 162 are arranged in the circuits for the actuating coils of the up and down direction switches respectively. The "selector" door lock control switches 158 and 163 are arranged in parallel relation in the circuit for the actuating coil of the cam motor switch. These circuits are clearly shown in the diagram in Figure 23, reference to which will be had later. 80

In operation, assume that the car is at the first floor as a home station and that, for example, the seventh floor car button has been pushed. The car, therefore, starts in the up direction. The manner in which the car is started in response to the pushing of a button will be described later. The selector machine operating shaft 217, driven by means of the steel tapes in the manner previously described, rotates screw 224 through beveled gears 228 and 226. The crosshead nut 233, therefore, is driven upwardly by screw 224 in proportion to the movement of the elevator car. Pawl magnet coil 241 being energized while the car is running, the pawl magnet armatures 246 and 247 are in their attracted positions and the pawls 258 and 260 do not engage the stopping collars. As the car reaches the seventh floor stopping zone, due to the fact that the seventh floor car button has been pushed, the pawl magnet coil 241 is deenergized. The operation of effecting the energization and deenergization of the pawl magnet will be described later. Pawls 258 and 260 are now forced out into their unattracted or stop positions by the armature weights and springs. This is the position illustrated in Figure 9. As the cross head is driven farther in the up direction, pawl 260 engages the seventh floor stopping collar 261 on tube 192. The tube 192 is then moved in the up direction with the crosshead, operating bell crank lever 182 to open the first slow-down switch 155, the second slow-down switch 156 and the stop switch 157 and door lock control switch 158 105 110 115 120 125 130

in the order named. The car, and therefore the crosshead, is then brought to a stop in a manner to be described later. It will be noted that the bell crank levers 182 and 196 are moved counterclockwise about their pivots, during the switch opening operation, moving tube 192 and consequently stopping collar 261 to the left. Thus, if there is excessive movement of the crosshead due to the fact that the car has not been stopped, no injury to the selector machine results because the stopping collar is finally withdrawn from operative engagement with the pawl by the movement of the levers. The back surface 264 of each pawl is so inclined that, for example in the above operation, as the back surface of pawl 258 strikes a stopping collar, the pawl slides over the collar without operative engagement. "Selector" switches 160, 161, 162 and 163 are opened, due to the connection between tubes 192 and 204, at the same time that switches 155, 156, 157 and 158 are opened. As the control circuits in which switches 160, 161, 162 and 163 are included are broken, due to the fact that the "director switch" is in up position, the opening of these switches is without effect at this time.

The "selector" switches are held in open position until the pawl magnet coil 241 is again energized. When this coil is energized, pawl 260 is withdrawn from operative engagement with the seventh floor stopping collar. Weight 211 then acts to move tube 192 downwardly and tube 204 upwardly until stopped by the engagement of screw stop 207 and cross rod end piece 210. Bell crank levers 182 and 201 are thus moved out of operative engagement with the abutment screws, permitting the "selector" switches to close.

Referring now more particularly to Figures 10 and 11, a plurality of bars 265 of insulating material are arranged between standards 150 and 151 to form mountings for the selector machine stationary contacts. Both of these standards are provided with a plurality of adjustable collars 266, the corresponding collars on each standard being arranged in horizontal alignment to support the insulating bars 265. The stationary contacts are arranged on the bars 265 in columns, designated as follows: 267, down hall stop contacts; 268, up hall stop contacts; 270, car stop contacts; and 271, reversing contacts. The stationary contacts are secured to the insulator bars 265 as by bolts 272. These bolts also secure insulating plates 273 on top of the stop contacts. Both up and down hall stop contacts and car stop contacts are provided for all the intermediate floors. The top floor down hall stop contact and bottom floor up hall stop contact may be omitted as no engagement is made with them during normal operation. Reversing

contacts are arranged only for the first and tenth floors.

The selector machine is provided also with moving contacts or brushes for engaging the various stationary contacts. These brushes are mounted on an insulating panel 274, the panel being secured, as by bolts 275, to lugs 276 formed on the crosshead frame 234. Two brushes, up car stop brush 277 and down car stop brush 278, are provided for engaging the car stop contacts in column 270. A single brush is provided for engaging the stationary contacts in the other columns; 280 being the down hall stop brush for engaging the contacts in column 267, 281 being the up hall stop brush for engaging the contacts in column 268, and 282 being the reversing brush for engaging the contacts in column 271. The system is arranged so that, of the stop brushes, only the up car stop and hall stop brushes are "alive" during up motion of the car and only the down car stop and hall stop brushes are "alive" during down motion of the car. The brushes are identical in construction, the details of one of the brushes being illustrated in Figures 12 and 13.

Referring to Figures 12 and 13, the brush contact pieces 283 are pivotally mounted in the brush frame 284, as by means of a pin 285 supported by the frame arms 286. The brush contact pieces are preferably provided with slots 287, through which the pivot pin 285 extends, so as to permit their longitudinal as well as pivotal movement. Longitudinal recesses 288 are formed in the brush contact pieces to receive springs 290. These springs abut yieldingly against pivot pin 285, tending to maintain the contact pieces in their outer position. The frame arms 286 and washer 291 close slots 287 to maintain the springs 290 in position.

A centering blade 292 for the brush contact pieces is loosely mounted on guide bushing 293. The bushing 293, along with a washer 294, is secured to the yoke 295 of the brush frame 284, as by means of a screw 296. A compression spring 297 is mounted on bushing 293 between centering blade 292 and washer 294. The outer end of the centering blade is bent in such manner as to form continuous engagement with the elongated surfaces of the contact pieces. Thus, when the brushes are not in engagement with a stationary contact, the centering blade tends to maintain the brush contact pieces in central position. Upon engagement of the brush and a stationary contact however, the contact pieces are rocked about their pivot pin 285, moving the outer end of the centering blade to the left, as viewed in Figure 13, against the force of compression spring 297. It will be observed that the centering blade acts as a lever, slidably pivoted against yoke 295, further to compress the spring 297 dur-

ing this operation. Thus, as the brush leaves the stationary contact, the compression spring causes the centering blade to restore the contact pieces to their central position.

5 As the circuit completed by the brush and stationary contact is from the frame and centering blade into the contact pieces, it will be seen that the circuit is not broken by rocking the contact pieces in either direction about 10 their pivot pin. In Figure 14, the up hall stop brush 281 is illustrated in rocked position in engagement with a stationary stop contact. The reversing brush 282 assumes a similar rocked position when in engagement 15 with one of its stationary contacts.

Referring to Figures 11 and 15, a pair of switches, 300 for the top floor and 301 for the bottom floor, are mounted on standard 20 148, the switches being of the same construction as the switch illustrated in Figure 7. Each switch is mounted on a plate 302 by means of through bolts 303. Each plate is 25 adjustably secured to the standard 148 by means of a U bolt 304. A cam 305 for engaging the rollers 107 of the switches is secured, as by screws, to a prong 306 of the forked end 232 of the crosshead. The switches 300 and 301 serve as limit switches 30 to cause the deenergization of the pawl magnet upon the car reaching the terminal landings as will be described later.

In operation, assume that the car has started from the first floor in response to the 35 third floor hall button. As the car moves in the up direction, the crosshead, and therefore the cam 305, brushes 277, 278, 280, 281 and 282 and pawl magnet 240, is moved upwardly in proportion to the movement of the elevator car, as has previously been explained.

40 If the up second floor hall button has not been pushed, the up second floor hall stop contact is "dead" so that the contact pieces for the up hall stop brush 281 strike the insulating bar 265, rock and sweep across the contact 45 without completing a circuit. As a result of the up third floor hall button having been pushed, the hall stop contact 310 in column 268 is rendered "alive". Thus as the brush 50 contact pieces of brush 281 sweep across contact 310, a circuit is completed for causing the deenergization of the pawl magnet coil. The position of the stopping collars 261 relative to the position of the stationary stop contacts is such that, for example in the case assumed, pawl 260 is released below the third 55 floor collar on tube 192. As the car continues its movement, the "selector" switches are opened in the manner previously described, causing the car to slow down and stop at the 60 third floor landing. The stop brush is carried past the stationary contact so that with the car at rest at a floor the relative position of the stop brushes and contacts is as illustrated in Figure 24.

65 If no other buttons have been pushed, the

car, after stopping at the third floor, is automatically started and proceeds to the tenth floor, as will be seen from later description. As the car approaches the tenth floor landing, the cam 305 engages the operating roller 107 70 for switch 300. The switch 300 opens, deenergizing the pawl magnet coil 241. The "selector" switches, therefore, are opened in the manner previously described. Although the selector machine may act to stop the car 75 at the terminal landings, it is preferred to employ the "director switch" for this purpose. The stop is insured, however, by the opening of the "selector" switches. Before the car reaches the tenth floor landing, brush 282 engages reversing contact 312, preparing a circuit for the "director switch" motor. This circuit is completed by one of the control switches during the stopping operation and the motor then moves the "director switch" 80 from "neutral" position, where it has been moved by the hatchway cam 87, into reversed position. As the "director switch" is moved into down position, the car starts in the down direction. If no buttons have been pushed, the car returns to the first floor, it having been assumed that the first floor is the home station, where it is again stopped and where the "director switch" is again reversed.

The reversing contacts are preferably 95 made longer than the stop contacts to insure their engagement by brush 282 when the control switches operate to complete the circuit for the "director switch" motor, these contacts and brush 282 being positioned so as to 100 remain in engagement with the car at rest at the floor. The stop contacts are made short in order to prevent response to late operation of a car or hall button. Otherwise the pawl 105 when released in response to the late operation of a push button might not engage the stopping collar for the floor for which the button was pushed and would then cause a false stop at the next floor. The brushes are 110 caused to rock and sweep across their corresponding contacts in order to insure positive engagement.

When the car is stopped at a terminal landing, for example floor ten, those brush contact pieces which are in engagement with 115 contacts are in a counter-clockwise rocked position. When the car starts in the down direction, these brush contact pieces must reverse, that is, rock into a clockwise position. In the event that any of the brush contact 120 pieces are caught in any manner, their reversal is permitted by slots 287 and springs 290.

The distance between the various stopping collars 261 is adjusted for the particular installation to correspond to the desired stopping distance from the floors, the insulating bars 265 being adjusted on standards 150 and 151, by means of collars 266, to correspond. The leads (not shown) for the pawl magnet 130

coil 241 are connected to certain of the binding posts on panel 274. The other binding posts are provided for the brushes mounted on the panel. Flexible conductors (not shown) extend from these binding posts to similar binding posts (not shown) on panel 314. The flexible conductors are suspended in very much the same manner that flexible cables are suspended from an elevator car.

10 Panel 314 is secured to standard 148 as by means of U clamps 315.

Reference may now be had to Figures 16 and 17 which illustrate the details of a preferred form of floor switch. The floor switches are identical in construction, one being provided for each push button. These switches are mounted on the "master" panel 316. The switch frame 317 is secured to the panel as by means of screws 318. The frame 20 supports two cores, 320 for the upper or closing coil 321 and 322 for the lower or reset coil 323. The middle portion 324 of the frame, extending outwardly between coils 321 and 323, forms a mounting on which a 25 plate 325 is secured, as by screws 326. This plate extends over a portion of the ends of both coils to retain them in position. A pin 327, supported by lugs 328 formed on plate 325, forms a pivotal mounting for the contact armature 330. The contact armature 330 extends upwardly to form an operating arm 331 for the movable contacts. The arm is T shaped, the movable contacts being supported by the cross member 332 of the T.

30 There are two movable contacts 333 and 334. Each movable contact is arranged to engage a stationary contact with the switch in closed position. As each pair of contacts is identical in construction, only the contacts of one pair will be described. Movable contact 333 is slidably mounted in an aperture 335 formed in one end of the cross member 332, being insulated therefrom by means of insulating bushing 336 and washer 337. The 35 bushing and washer are mounted on the contact stem 338 with the flange 340, formed on bushing 336, abutting against the contact block 341. Nuts 342 serve to hold the contact parts in assembled relation and to bind 40 the terminal clip 343 to the contact. The cross member 332 is arranged between flange 340 and washer 337, being maintained against washer 337 with the switch in open position by means of a spring 344.

45 A support 345 for the stationary contact 346 is mounted on panel 316, stationary contact 346 being arranged for engagement by movable contact 333 and stationary contact 347 (not shown) by movable contact 334.

50 The support is secured at the rear of the panel as by a nut 348. The contact end of support 345 is threaded to receive the stem 350 of the holder 351 for contact block 352. Thus the position of the stationary contact 55 346 relative to the position of the movable

contact 333 may be adjusted, a nut 353 being provided on stem 350 for locking the stationary contact in adjusted position.

A pin 354, supported by additional lugs 355 formed on plate 325, forms a pivotal 70 mounting for the latching member 356. This latching member, preferably of non-magnetic material, comprises a pair of arms 357 and 358, through which pivot pin 354 extends and connecting yokes 360 and 361. The 75 latching member is biased by weights 362, formed on arms 357 and 358, to turn counterclockwise, as viewed in Figure 17, the movement being limited by the engagement of a lug 363, formed on the inner side of arm 357, 80 and one of the mounting lugs 355. A projection 364, extending upwardly from the top yoke 360, cooperates with a lug 365, depending from the horizontally extending arm 366 of contact armature 330, to latch the contacts 85 333, 346 and the contacts 334, 347 in closed positions.

The armature 367 for the reset magnet is pivotally mounted on pin 354 between the lugs 355. A lug 368 extends upwardly from the pivot point of the reset armature 367 to receive an adjustable abutment screw 370. A biasing weight 371, formed on the lower end of reset armature 367, tends to maintain the armature in unattracted position with screw 90 370 abutting against the projection 372 formed on the extended portion 324 of frame 317. A lug 373, formed on the arm 357, extends in the path of the weight 371, to be struck thereby as the reset armature 367 is 95 moved into its attracted position.

The bottom yoke 361 is formed with a depending lug 374 in which a movable contact 375, identical in construction with movable contacts 333 and 334, is slidably mounted. The contact support 376, for the stationary contact 377, is identical in construction with the contact supports for the stationary contacts 346 and 347, except that it is shortened. The support is similarly secured at the rear 100 of the panel 316 by a nut 348. The arms 357 and 358 and bottom yoke 361 are so formed as to permit the engagement of the lug 373 formed on arm 357 by weight 371 as above set forth. With contact 375 in engagement 105 with contact 377 and the forward contacts separated, lug 365 rests in notch 378, latching the back contacts 375, 377 in closed position.

Non-magnetic plates 379, provided on the outer ends of cores 320 and 322, serve as spacing members to prevent the armatures 330 and 367 from being held in by residual magnetism. The terminals 380, provided on the coils 321 and 323, and the binding nuts 381, provided on the ends of the contact supports 110 125 extending to the rear of the panel, are for connecting the switch in the system, the connections to be described along with the description of the wiring diagram in Figure 24.

In operation, with the closing coil 321 en- 130

ergized in response to the pushing of a button, contacts 333 and 334 are moved into engagement with their corresponding stationary contacts 346 and 347, spring 344 yielding 5 to permit the engagement of contact armature 330 and non-magnetic plate 379. With the contact armature in this attracted position, the latching member 356 is free to move into position with projection 364 beneath lug 10 365, and the latch for contacts 375, 377 is released. Thus the contacts 375, 377 separate and the projection moves under lug 365, the movement being caused by the action of gravity on the weights 362 and the lower portion 15 of the latching member. It is to be noted that the latch for the back contacts is not released until the latching member is free to move into position for latching the forward contacts in engagement. Upon de- 20 energization of coil 321, contact armature 330 is moved outwardly by the action of spring 344 to cause the engagement of lug 365 and projection 364. As this movement is insufficient to cause the engagement of the 25 cross member 332 and the washers 337, the contacts 333, 346 and 334, 347 are latched in closed position. This is the position illustrated in these figures.

Upon the energization of reset coil 323, the 30 reset armature 367 is moved into attracted position. This armature gains in speed as it is pulled in so that the weight 371 strikes lug 373 a hammer blow. This blow insures the tripping out of the latch for the forward 35 contacts. At the same time the back contacts are closed. Contact armature 330 now falls under the action of gravity into the notch 378 separating the forward contacts and latching the back contacts in engagement. 40 The outward movement of the armature 330 is limited by the engagement of lug 365 with the bottom of the notch.

Referring to Figure 18, the floor switches which operate in response to the hall buttons 45 are arranged on "master" panel 316 in accordance with the floors, those for the intermediate floors being arranged in pairs. The floor switches which operate in response to the car buttons are arranged in groups, the 50 number of the groups being in accordance with the number of elevators installed in the bank. The switches have been characterized generally in accordance with the floor and circuit in which they are included. For example, DH 2 indicates that the switch is in 55 the down second floor hall button circuit and IC 3 indicates that the switch is in the third floor car button circuit for Elevator No. 1. Rotatable switches 385, two for each elevator, 60 also are mounted on panel 316. Each switch has four positions which, for convenience of description, are characterized, *a*, *b*, *c* and *d*. The significance of these positions and the purpose of these switches will be explained 65 later. The home station switches 386 also are

mounted on this panel. These switches are rotatable and one is provided for each elevator. Each switch has ten operative positions corresponding to the floors in the particular installation and an off position. Six 70 electromagnetic relays, UU, VV, WW, XX, YY, and ZZ are mounted on this panel, UU, VV and WW for Elevator No. 1 and XX, YY and ZZ for Elevator No. 2. The purpose of the home station switches and the relays 75 will be set forth in detail as the description proceeds.

Reference may now be had to Figures 19, 20 and 21 which illustrate the preferred form of time switch. The switch, designated 80 as a whole by the numeral 390, is mounted on a panel 391, the panel being mounted on the framework which supports the panel for the control switches. The switch is operated by a motor 392 mounted on panel 391. A coupling flange 393 is secured to the lower end of the motor shaft 394 as by a pin. This flange is connected in driving relation to a second coupling flange 395 as by means of the pin 396. The flange 395 is secured by a 90 pin to the vertical shaft 397. This shaft is supported by a bearing 398 formed on the supporting plate 400. A collar 401 is pinned to the shaft 397 below the bearing 398. Below the collar 401 is a worm 402, the worm 95 being held in position on the shaft 397 by means of a nut 403 and pin 399. This worm is driven through the collar 401 by means of a key 404 formed on the collar, the key extending into a slot in the worm. The worm 100 drives a worm gear 405 secured, as by a pin, to a horizontal shaft 406. This shaft is supported by a bearing formed in the hanger 407. On the side of the hanger opposite the worm gear the shaft 406 is provided with a collar 105 408. A driving relation is effected between the collar 408 and another worm 410 provided on shaft 406 in a similar manner to that effected between collar 401 and worm 402. The worm 110 410 drives another worm gear 411 pinned to another vertical shaft 412. A flange 413 is provided on shaft 412 above the supporting plate for retaining the shaft in position within the bearing 414 and therefore for retaining the driving relation between worm 115 410 and gear 411. The gearing below plate 400 is enclosed by an oil pan 415, the pan being secured to the plate as by means of screws 416.

A bell crank lever 417 is pivotally mounted 120 on the vertical shaft 412. The arm 418 of the bell crank lever which extends toward the panel 391 is provided with a pin 420. An idler gear 421 is rotatably mounted on this pin, the idler being driven by means of a gear 125 422 pinned to shaft 412 above the lever 417. This idler gear is moved into operative engagement with a gear 423 by means of what may be termed a clutch magnet 424. The clutch magnet is secured to the plate 400, its 130

mounting frame 425 being provided with depending arms 426 for pivotally supporting a bell crank lever 427. The stem 428 of the magnet plunger 430 extends through an aperture 5 431 in the horizontal arm 432 of the lever 427 and is provided at its lower end with a washer 433 positioned by pin 434. A spring 435 is arranged on the stem between the washer and the horizontal arm 432. The 10 vertical arm 436 of the lever 427 is connected by link 437 with the other arm 438 of bell crank lever 417.

The gear 423 is secured to a bushing 440, the bushing being rotatably mounted on a 15 pin 441 secured in plate 400. The bushing forms a guide for a torsion spring 442. One end of this spring is secured to plate 400 and the other end to the gear 423. The gear 423 is provided with a plurality of apertures 443 arranged in an inner circle about the pin 441. Each aperture is threaded so as to receive a stop pin 444 and a trip pin 445, the stop pin being screwed into the desired aperture from the bottom of the gear and 25 the trip pin from the top.

The trip pin 445 is arranged to engage a block 446, of insulating material, secured to the bottom side of the end of arm 447. The arm 447 is pivoted at its inner end on a pin 30 448 secured to the bracket 450, being positioned by the washer 451 and pin 452. A second torsion spring 453 is arranged between the arm 447 and bracket 450, a guide 454 for the spring being formed on the arm 35 447. One end of the spring is secured to the arm and the other end to the bracket. Projections 455 are formed on the inner end of arm 447 to form stops.

The bracket 480 also pivotally supports 40 the contact lever 456 for the movable contact 457. This contact may be of any suitable construction, its stem 458 being provided with a nut 460 for securing the contact to the lever and for attaching the clip 461 for conductor 462. The movable contact normally engages 45 a stationary contact 463, this latter contact being supported by a contact holder 464 secured to panel 391. The lower arm 465 of lever 456 is arranged to pivotally support the 50 operating arm 466, an aperture being provided for receiving the pivot pin 467. The upper end of arm 466 is provided with lugs 468 and 469 for engaging the projection 470 on lever 456 to cause the operation of the 55 switch. A tension spring 471 is secured at one end to a lug 472 formed on the upper end of arm 466 and at the other end to a similar lug 473 formed on the outer end of arm 447.

The conductor 462 is provided at its other 60 end with a clip 474 secured to one of the screws 475 provided for mounting the bracket 450 on the panel. This screw is provided with nuts 476 at the rear of the panel for connecting the switch in the system. Similarly, one 65 of the screws 477 for mounting the contact

holder 464 on the panel is provided with nuts 478 at the rear of the panel, also for connecting the switch in the system. Binding posts 480 are provided on the panel for connecting the operating motor and clutch 70 magnet coil 483 in the system. Bolts 481 are for securing the supporting plate 400 to the panel. The portion of the mechanism above the supporting plate is enclosed by a cover 75 482.

In operation, assume that the clutch magnet coil 483 and motor 392 are energized. The plunger 430 therefore has been pulled up within the coil, acting through washer 433 to compress spring 435. Also the levers 417 80 and 427 and link 437 have been moved into position to cause the engagement of idler gear 421 with gear 423. This is the position of the parts as illustrated in the figures being described. The motor 392, therefore, operates through the train of gears to cause the rotation of gear 423. The apertures 443 in the gear 423 are so positioned that, with the speed reduction obtained through the train 85 of gears, each successive aperture represents an additional half minute in the time interval to be obtained. With the trip pin 445 in the position illustrated, four minutes will elapse after the energization of the motor and clutch magnet coil before the switch contacts are separated. Toward the end of the 90 four minute interval, the trip pin 445 engages the block 446 causing the outer end of arm 447 to move to the right as viewed in Figure 21. Continued movement of the arm causes 95 the lug 473, and therefore the bottom end of spring 471, to approach the center line of arm 466. As the center line is reached and even passed, it will be seen from the illustration 100 that the center line of the spring has not reached the pivot point for contact lever 456. Thus, the force of the spring still tends to keep the switch contacts in engagement, eliminating chattering and burning of the contacts. As the lug 473 passes the center 105 line of arm 466, the spring 471 causes clockwise movement of the arm. The upper end of the arm 466 gains in speed during this movement so that lug 468 strikes projection 470 a hammer blow, causing quick separation 110 of the switch contacts 457, 463. As a result of the separation of the contacts, the motor 392 and clutch magnet coil 483 are deenergized. The plunger 430 of the clutch magnet drops by gravity and, aided by spring 435, 115 strikes the arm 432 of lever 427 a hammer blow, insuring the disengagement of the idler gear 421 from gear 423. It is to be noted that the torsion springs 442 and 453

are wound up during the switch opening operation, spring 442 returning gear 423 to "normal" position upon the release of the idler gear 421. As this "normal" position is reached, the stop pin 444 engages a bumper 484, comprising for example a piece of felt 120 125 130

485 reinforced by projection 486 formed on plate 400, damping the stop. Torsion spring 453 overcomes the force of spring 471 as the trip pin 445 is withdrawn, causing the 5 turn of arm 466. As the arm moves back into its former position, lug 469 strikes projection 470, causing the reengagement of the switch contacts. It is believed obvious from the above description that deenergization of 10 the motor 392 and clutch magnet coil 483, at any time after their energization, causes the return of those parts, which have moved, to their "normal" position, regardless of the extent of the movement or of the time that 15 deenergization occurs.

The control panel 496 for Elevator No. 1 with its various control switches is illustrated in Figure 22. The electromagnetic switches provided on this board have been 20 designated as follows:

- A—potential switch
- B—up direction switch
- C—down direction switch
- D—first accelerating switch
- E—second accelerating switch
- F—third accelerating switch
- G—maintaining relay
- H—motor field switch
- I—door contact relay
- J—minimum current field relay
- K—driving motor starting switch
- L—driving motor running switch
- M—driving motor starting relay
- N—protective relay
- O—accelerating relay
- P—up direction relay
- Q—down direction relay
- R—slow down switch
- S—load switch
- T—leveling switch motor relay
- U—home station relay
- V—cam motor switch
- W—time relay
- X—series field relay
- Y—series field switch
- Z—speed control relay
- LU—up slow speed leveling relay
- LD—down slow speed leveling relay
- LF—fast speed leveling relay
- DP—dash pot relay
- SS—stop switch

Throughout the description which follows, these letters, in addition to the usual reference numerals, will be applied to the parts of the 5 above enumerated switches. For example, contacts B 662 are the contacts on the up direction switch, while actuating coil A 604 is the coil that operates the potential switch. It will be assumed that the control switches 10 497 and 498 arranged on the control panel are closed.

Reference may now be had to Figures 23 and 24 which illustrate diagrammatically the various control and power circuits. No 15 attempt is made in these figures to show the

coils and contacts of the switches in their associated positions, "straight" diagrams being employed wherein the coils and contacts of the various switches are separated in such a manner as to render the circuits involved 70 relatively simple. For a clearer understanding of the invention, the stationary contacts of the switches are illustrated in cross section. The relation of the coils and their contacts may be seen upon reference to Figure 75 22. It will be observed that Figure 23, taken in connection with the top portion and the left half, below the legend "Selector machine, Elevator No. 1," of Figure 24, constitutes a complete wiring diagram for one elevator 80 85. The top portion and the right half, below the legend "Selector machine, Elevator No. 2," of Figure 24 show a portion of the control circuits, particularly the push button control circuits, for a second elevator, it being understood that the second elevator is provided with additional control and power circuits identical with that illustrated in Figure 23. The lowermost control line 813 in Figure 24 is common to the two elevator 90 systems as will be seen from later description. As much of the diagram as relates to floors 5 to 9 inclusive has been omitted in Figure 24 since it is believed that the invention will be clear without the additional illustration 95 and that the diagram will be much simpler.

Referring particularly to Figure 23, the motor-generator set, as illustrative of one form of power supply suitable for the present system, comprises an alternating current driving motor 500 and a variable voltage direct current generator 501. 502, 503 and 504 are alternating current mains for supplying power to the driving motor, resistances 505 being arranged in the mains for starting purposes. The elevator motor is designated by the numeral 506. An exciter 507, driven by the motor 500, is employed to supply current for the separately excited fields, 508 for the generator and 510 for the elevator motor, and 100 for certain of the control circuits. The other control circuits are supplied from the alternating current mains. The generator is provided also with a series field 511. The exciter is provided with a shunt field 512 and a 105 series field 513. The armature of the exciter is designated by the numeral 509. Discharge resistances 514 and 515 are provided for the separately excited fields of the generator and elevator motor respectively. A resistance 516 110 is arranged in shunt to the generator series field. A resistance, arranged in sections 517, 518, 520, 521, 522, 523, 524, 525, 526 and 527, is provided for controlling the strength of the generator separately excited field and therefore the voltage applied to the elevator motor armature. Resistances 528 and 529 are arranged in series with the elevator motor field. 530 is the release coil for the elevator motor electromagnetic brake. Coil 530 is provided 115 120 125 130

with discharge resistances 531, 532 and 533 for controlling the application of the brake under different conditions of operation. Coil 530 is provided also with a cooling resistance 534. 536 is the armature and 537 is the field of the motor 535 for moving the rollers of the leveling switch so as to clear the leveling cams. The armature of the door lock cam motor 538 is designated by the numeral 540, the field being designated 541. Various safety and emergency switches and door and gate contacts may be employed, reference to which may be had in connection with the description of the various circuits and of the operation of the system. The electromagnetic switches are shown in their deenergized positions.

Referring now also to the left half of Figure 24, assume that the home station for Car No. 1 is at the first floor, the home station switch 386 for Elevator No. 1 being illustrated in that position, and that the car is at rest at the home station as indicated by the position of Elevator No. 1 selector machine brushes. The "director switch", therefore, is in its up position with segment 54 bridging contacts 50, 43, 46 and 47. Assume further that the motor-generator set is not in operation and that a prospective passenger desires to be carried from the first to the fourth floor. Due to the fact that the door lock cam motor is not energized, the first floor well door is unlocked and the first floor door contacts are separated. The contacts of the various well doors are arranged in series relation and are indicated by a single pair of contacts 542. Contacts 542, therefore, are separated. The prospective passenger may therefore open the well door at the first floor and step into the car. It is preferred to provide the car with a movable platform switch (see Figure 1). Due to the weight of the passenger now in the car, contacts 543 and contacts 544 of the platform switch are separated. The passenger now closes the gate, causing the engagement of gate contacts 545 and 546, by-passing contacts 543 and 544 respectively. The doors are arranged to close automatically, as by a spring. The door contacts, however, remain separated, due to the fact that the door lock cam motor has not been energized. Upon the fourth floor car button being pushed, the car button four floor switch closing coil 321 is energized. The circuit for this coil may be traced from alternating current power main 502, line 547 (connecting Figures 23 and 24), line 548, line 550, push button 551, coil 321, back contacts 375, 377, line 552, line 553 (connecting Figures 24 and 23), to alternating current power main 503. The floor switch operates in the manner previously described to cause the engagement of forward contacts 333, 346 and 334, 347 and the separation of back contacts 375, 377. The

purpose of the back contacts 375, 377 is to prevent further response of the floor switch to the pushing of the fourth floor car button until the stop for the fourth floor is initiated. In this manner the floor switches are saved from wear due to unnecessary operation. The forward contacts 333, 346 prepare a circuit for the fourth floor car stop contact 554 rendering it "alive". The forward contacts 334, 347 complete a circuit for a portion of coil 75 VV 822 of Elevator No. 1 service relay and coil UU 555 of the car button relay. This circuit may be traced from main 502, line 547, line 556, by way of line 557 through contacts 334, 347 and resistance 825, back to line 80 556 through a portion of coil VV 822, the remaining portion of coil VV 822 being short-circuited by arm 817 of one of the switches 385 for Elevator No. 1, and through coil UU 555, line 558, line 553, to main 503. Elevator No. 1 service relay VV does not operate at this time as insufficient current is supplied to the active portion of its actuating coil. The car button relay, however, operates to cause the engagement of contacts 85 UU 560 to prepare certain of the control circuits and of contacts UU 561 to complete a circuit for the actuating coil M 562 of the driving motor starting relay. This circuit may be traced from main 504, by way of line 90 563 through protective relay contacts N 564, line 565, by way of line 566 through contacts UU 561, control switch 497 and coil M 562, line 553, to main 503. Relay M operates to cause the engagement 100 of contacts M 568, M 570, M 571 and M 572. The engagement of contacts M 571 prepares a circuit for the actuating coil L 573 of the driving motor running switch. The engagement of contacts M 572 prepares a circuit for 105 the actuating coil SS 574 of the stop switch. The engagement of contacts M 570 completes a circuit for the actuating coil DP 575 of the dash pot relay. The circuit for coil DP 575 may be traced from the main 502, line 547, by 110 way of line 576 through contacts M 570, motor field switch contacts H 577, stop switch contacts SS 578 and coil DP 575, line 558, line 553, to main 503. The dash pot relay DP has a certain time element, for example ten 115 seconds, depending on the requirements of the particular installation. A circuit is completed for the actuating coil K 580 of the driving motor starting switch upon the engagement of contacts M 568 which circuit may be 120 traced from alternating current main 504, by way of line 563 through contacts N 564, contacts M 568, coil K 580 and contacts L 581, line 553, to main 503. The switch K operates immediately to cause the engagement of contacts K 582, K 583 and K 584 connecting the stator of the driving motor to the power mains through resistances 505 and completing the circuit for coil L 573. The circuit for coil L 573 may now be traced from main 502 125 130

through contacts K 582, one of the resistances 505, by way of line 585 through coil L 578 and contacts M 571, another one of the starting resistances 505, contacts K 583, to main 5 503. The switch L, however, does not operate immediately, the voltage applied to its actuating coil being of low value due to the high potential drop over resistances 505 during the starting of the motor. As the driving 10 motor approaches full speed, the current in the stator winding is reduced raising the voltage across coil L 578, causing the switch L to operate. The switch L, upon operation, causes the engagement of power contacts L 15 586, L 587 and L 588 to by-pass resistances 505, connecting the driving motor directly to the alternating current mains, and the engagement of auxiliary contacts L 590 to prepare a circuit for the actuating coil G 591 of 20 the maintaining relay. Also the switch L causes the separation of auxiliary contacts L 581 to deenergize coil K 580 and of auxiliary contacts L 593 to remove the short circuit for the actuating coil J 594 of the minimum 25 current field relay. The switch K drops out separating contacts K 582, K 583 and K 584 to disconnect resistances 505 from the mains. The operation of relay J will be explained later.

30 The E. M. F. of the exciter 507 builds up to its full value as the driving motor 500 comes up to full speed. As has been stated previously, the exciter supplies current to the field 510 of the elevator motor 506. According 35 to the preferred arrangement, however, with the motor generator set running but with the elevator motor at rest, this current is reduced providing what may be termed a "standing field". The resistance 528 is employed for this purpose. The elevator motor field circuit may be traced from the left hand (+) exciter terminal 595, line 596 by way of line 597 through field 510, coil J 594, resistance 528 and through contacts Z 598 of the 40 speed control switch and contacts F 600 of the third accelerating switch arranged in parallel relation, line 601, to right hand (-) exciter terminal 602. It is not desired to apply full exciter voltage to the field 510 45 when the elevator motor is not in operation because of increased power consumption. On the other hand, it is not desired to have the field 510 deenergized with the elevator motor at rest as a matter of safety and because of 50 the large time constant involved in building up.

55 As has previously been explained, contacts L 593 separate as the driving motor 500 comes up to full speed. The actuating coil J 594 of the minimum current field relay, therefore, does not receive current until the exciter E. M. F. is built up to substantially full value. Until the elevator motor field builds up however, this current is of insufficient value to 60 cause the operation of relay J. As soon as

the elevator motor field builds up substantially to full "standing field" value, relay J operates to cause the engagement of contacts J 603. The circuit for the potential switch actuating coil A 604 is completed upon the engagement of contacts J 603 and may be traced from terminal 595, line 596, by way of line 605, through switch 498, contacts A 606, contacts J 603, coil A 604, various safety switches (indicated by legend) and safety switch 607 70 in the car, line 601 to terminal 602. Thus the circuit for coil A 604 cannot be completed and therefore the potential switch cannot operate until the exciter E. M. F. has built up substantially to full speed and until the elevator motor field 75 80 85 90 95 100 105 110 115 120 125 130 510 has built up substantially to full "standing field" value.

Assuming then that contacts J 603 are in engagement and that coil A 604 is energized, the potential switch operates to cause the engagement of contacts A 608, A 610 and A 611 and the separation of contacts A 606. The engagement of contacts A 608 and A 610 prepares the circuit for the generator separately excited field and various control circuits, completes a circuit for the actuating coil G 591 of the maintaining relay and, assuming that gate contacts 545 are closed, completes a circuit for the actuating coil P 612 of the up direction relay. The engagement of contacts A 611 connects the discharge resistances 532 and 533 in parallel across the brake release coil 530. The separation of contacts A 606 inserts the cooling resistance 613 in series with the actuating coil A 604.

The circuit for coil P 612 may be traced from terminal 595, by way of line 596 through contacts A 608, by way of line 614 through coil P 612, line 615, "director switch" contacts 48, 50 bridged by segment 54, line 616, by way of line 618 through contacts UU 560 and gate contacts 545, safety switch 607, line 605, line 601, to terminal 602. The relay P, upon operation, causes the engagement of contacts P 622, contacts P 623 and contacts P 664, the engagement of contacts P 622 preparing the circuit for the actuating coil B 624 of the up direction switch and the actuating coil H 625 of the motor field switch, the engagement of contacts P 623 preparing the circuit for the pawl magnet coil 241 and the engagement of contacts P 664 preparing a circuit for the up car stop and hall stop brushes 277 and 281, rendering them "alive". The circuit for coil G 591 may be traced from terminal 595, by way of line 596 through contacts A 608, by way of line 626 through coil G 591 and contacts L 590, by way of line 601 through contacts A 610, to terminal 602. Relay G, upon operation, causes the engagement of contacts G 627 and G 628, contacts G 627 completing the circuit for the motor 392 and clutch magnet coil 483 of the time switch and contacts G 628 establishing a by-pass for contacts UU 561 through

the time switch contacts 457 and 463. The circuit for motor 392 and coil 483 may be traced from terminal 595, by way of line 596 through contacts A 608, by way of line

5 630 through the armature 631 and field 632 of the motor 392, clutch magnet coil 483, contacts G 627 and contacts W 633 of the time relay, by way of line 601 through contacts A 610, to terminal 602. The completion 10 of this circuit serves no particular purpose at this time as the circuit is almost immediately broken by the separation of contacts W 633 as will be seen later.

The dash pot relay DP has been slowly 15 operating during this time. Upon the engagement of its contacts DP 634, a circuit is completed for the stop switch actuating coil SS 574. This circuit may be traced from alternating current main 502, line 547, by 20 way of line 635 through contacts M 572 and contacts SS 636, line 637, contacts DP 634, coil SS 574, line 558, line 553, to main 503. The switch SS, upon operation, causes the separation of contacts SS 636 and contacts 25 SS 578 and the engagement of contacts SS 638 and contacts SS 640. The engagement of contacts SS 640 establishes a maintaining circuit for the actuating coil SS 574 through line 641. The separation of contacts SS 636 30 inserts a cooling resistance 642 in series with the actuating coil SS 574. The separation of contacts SS 578 breaks the circuit for the dash pot relay coil, the relay, not being retarded in opening, dropping out immediately 35 ly to separate contacts DP 634. The engagement of contacts SS 638 completes the circuit for the pawl magnet coil 241. This circuit may be traced from terminal 595, by way of line 596 through contacts A 608, by way 40 of line 643 through accelerating relay contacts O 644, coil 241 and contacts SS 638, by way of line 645 through contacts P 623 and switch 300, line 646, contacts UU 560, by way of line 618 to terminal 602 as previously 45 traced.

Upon the energization of its coil, the pawl magnet retracts its pawls 258 and 260 permitting the "selector" switches to close. "Selector" door lock control switch 158, upon 50 closing, completes a circuit for the actuating coil V 647 of the cam motor switch and the actuating coil W 648 of the time relay. This circuit may be traced from terminal 595, by way of line 596 through contacts A 608, by 55 way of line 650 through coil W 648, coil V 647 and switch 158, contacts UU 560, by way of line 618 to terminal 602 as previously traced. Relay W, upon operation, causes the separation of contacts W 633 in the circuit for 60 the time switch motor 392 and clutch magnet coil 483. Switch V, upon operation, causes the engagement of contacts V 651 completing the circuit for the door lock cam motor 538. This circuit may be traced from terminal 595, by way of line 596 through contacts A 608, by

way of line 652 through the armature 540 and field 541 of the door lock cam motor and contacts V 651, by way of line 601 through contacts A 610, to terminal 602.

Referring briefly to the system for Elevator 70 No. 1 in Figure 1, the door lock cam motor 538 operates through linkage 653 to withdraw the retiring cam 654 from engagement with roller 655 on the door lock lever 656. The lever 656 then acts to cause the engagement of the 75 door contacts for that floor and the locking of the door. As illustrated, a door lock lever and door contacts are provided for each floor, each lever being pivotally mounted on its 80 respective door. Each lever is arranged so that the effect of gravity tends to cause the engagement of the door contacts. The door locking mechanism is not shown, this mechanism and the door contacts being of any well known construction. Referring back to Figures 23 and 24, the contacts 542, representing all the door contacts connected in series relation, are now closed, completing the circuit for the door contact relay actuating coil I 85 657. This circuit may be traced from terminal 595, by way of line 596 through contacts A 608, by way of line 620 through door contacts 542 and coil I 657, by way of line 601 through contacts A 610, to terminal 602. Relay I, upon operation, causes the engagement of 90 contacts I 658 and I 660. The engagement of contacts I 658 has no effect when the "director switch" is in up position. The engagement of contacts I 660 completes the circuit for the up direction switch coil B 624 and 100 motor field switch coil H 625. This circuit may be traced from terminal 595, by way of line 596 through contacts A 608, by way of line 661 through gate contacts 546, coil H 625, coil B 624, contacts I 660, contacts P 622 105 and up "selector" stop switch 157, line 615, "director switch" contacts 48, 50 bridged by segment 54, line 616, by way of line 618 to terminal 602 as previously traced.

It is preferred to provide the direction 110 switches with a mechanical interlock to prevent their simultaneous operation. Such an interlock may be of the form of a walking beam pivotally mounted for engaging catches on the plungers of the direction switches as illustrated in Figure 22. It is to be noted that, although the down "selector" switches are closed, no circuit can be completed by them since the "director switch" is in up position. Upon operation of the up direction switch in 115 response to the energization of its actuating coil B 624, contacts B 662 and contacts B 663 engage completing the circuit for the generator field 508 and contacts B 666 separate, these contacts being in the circuit for the "director switch" motor. The purpose of contacts B 666 will be seen from later description. The circuit for the generator field may be traced from terminal 595, by way of line 596 through contacts A 608, line 667, by way 120 125 130

of line 668 through slow down switch contacts R 670 shunting resistance sections 517 and 518, by way of line 671 through resistance sections 520, 521, 522 and 523, load switch contacts S 672 shunting resistance section 524, speed control switch contacts Z 673 shunting resistance section 525, resistance sections 526 and 527 and contacts B 662, by way of line 674 through field 508, by way of line 10 675 through contacts B 663, by way of line 601 through contacts A 610, to terminal 602.

The motor field switch H operates simultaneously with the direction switch B. Switch H upon operation causes: the separation of contacts H 676 to disconnect the generator field 508 from the generator, of contacts H 677 to disconnect the resistance 533 from across the brake release coil 530 and of contacts H 577 in the circuit for the dash pot relay coil DP 575; and the engagement of contacts H 681 to by-pass contacts UU 560, of contacts H 682 to complete the circuit for the brake release coil 530 and the actuating coil U 685 of the home station relay and of contacts H 683 to 20 short-circuit resistance 528 in the circuit for the elevator motor field 510 permitting the motor field to build up to its full strength. The purpose of contacts H 577 and H 676 will be seen from later description. Resistance 30 533 being of low value, its disconnection before contacts H 682 engage prevents excess power consumption from lines 596-601. Contacts H 677 and resistance 533 will be referred to again during the description of the stopping of the car. The purpose of by-passing contacts UU 560 will be explained later. The circuit for the brake release coil 530 and coil U 685 may be traced from terminal 595, by way of line 596 through contacts A 608, by 40 way of line 684 through brake release coil 530, Elevator No. 1 home station relay actuating coil U 685, brake contacts 686 (shown diagrammatically in proper relation in Figure 1) and contacts H 682, by way of line 601 through contacts A 610, to terminal 602.

The home station relay operates to cause the engagement of contacts U 687 completing a circuit for the closing coil 321 of the car button first floor switch. This circuit may 50 be traced from alternating current main 502, line 547, by way of line 688 through contacts U 687, home station switch contact arm 690 and first floor contact 691, line 692 (thus bypassing the first floor car button 693), coil 55 321, contacts 375, 377, line 552, line 553, to main 503. The floor switch operates in the manner previously described to cause the engagement of forward contacts 333, 346 and 334, 347 and the separation of back contacts 60 375, 377. The engagement of contacts 333, 346 prepares a circuit for the first floor car stop contact 694 rendering it "alive." As all the contacts 334, 347 of the car button floor switches are arranged in parallel relation in 65 the circuit for the car button relay coil UU

555 and Elevator No. 1 service relay coil VV 822, the engagement of contacts 334, 347 of the car button first floor switch simply establishes an additional path comprising resistance 826 for the current supplied to these 70 coils. The current supplied to the active portion of coil VV 822, however, is still insufficient to cause the operation of the service relay.

The brake release coil 530 being energized, the elevator motor field 310 being connected directly to lines 596-601 and current being supplied from the armature 695 of the generator 501 to the armature 696 of the elevator motor 506, due to the generator field 508 being energized, the elevator motor starts. The circuit for the elevator motor armature may be traced from the upper generator armature terminal by way of line 697 through generator series field 511 shunted by a portion of resistance 516 and contacts Y 698 of the series field switch, protective relay coil N 700, elevator motor armature 696 and load switch current coil S 701, back to the generator armature 695. As the brake releases, the brake switch contacts 686 separate inserting cooling resistance 534 in series with the brake release coil 530 and breaking the circuit for coil U 685. Thus the shunt circuit around the coil O 702 is removed permitting the operation of the accelerating relay O. The circuit for coil O 702 may be traced from terminal 595, by way of line 596, through contacts A 608, by way of line 684 through the brake release coil 530, resistance 531 and resistance 532, arranged in parallel relation, by way of line 707 through coil O 702, back to line 684, contacts H 682, by way of line 601 through contacts A 610, to terminal 602. The operation of relay O causes the separation of contacts O 644 to insert cooling resistance 680 in series with the pawl magnet coil 241 and the engagement of contacts O 708 to complete the circuit for the first accelerating switch actuating coil D 710 and the leveling switch motor relay actuating coil T 711. The purpose of this arrangement is to utilize the time constant of the brake for timing the acceleration of the motor, more specifically for timing the operation of the first accelerating switch. Although the brake release coil 530 is energized at the same time that power is supplied to the motor, the brake shoes do not lift at once because of the inherent time constant of the brake magnet and because the brake shoes and lever arms (not shown in Figure 1, the brake being represented by a coil, plunger, spring and single shoe) represent considerable mass to be set in motion. The circuit for coils D 710 and T 711 may be traced from terminal 595, by way of line 596 through contacts A 608 by way of line 704 through contacts O 708, coil T 711 and coil D 710, by way of line 712 through up "selector" second slow down switch 156, 130

"director switch" contacts 46 and 50 bridged by segment 54, line 616, by way of line 618 to terminal 602 as previously traced.

The energization of the first accelerating switch actuating coil D 710 causes the engagement of contacts D 713 and D 714. Contacts D 713 short-circuit resistance sections 520 and 521 in the circuit of generator field 508 increasing the generator E. M. F. causing an increase in the speed of the elevator motor. It is to be noted that the circuit completed by contacts D 713 also shunts resistance sections 517 and 518, previously referred to as shunted by contacts R 670. Contacts D 714 complete the circuit for the actuating coil E 716 of the second accelerating switch.

The energization of the leveling switch motor relay coil T 711 causes the engagement of contacts T 717. A circuit is completed for the leveling switch motor 535 by contacts T 717 and may be traced from terminal 595, by way of line 596 through contacts A 608, by way of line 718 through the leveling switch motor armature 536 and field 537 and contacts T 717, by way of line 601 through contacts A 610, to terminal 602. The leveling switch motor acts to move the leveling switch operating rollers so as to clear the leveling cams. The operation of the leveling switch and leveling switch motor will be set forth more in detail during the description of a stopping operation.

The circuit for coil E 716 may be traced from terminal 595, by way of line 596 through contacts A 608, by way of line 720 through contacts D 714, resistance 721, reactance 722 and coil E 716, by way of line 723 through up "selector" first slow down switch 155, "director switch" contacts 47 and 50 bridged by segment 54, line 616, by way of line 618 to terminal 602 as previously traced. The switch E does not operate immediately the circuit for its actuating coil is completed, its action being delayed by the reactance 722. Upon operation, contacts E 724 engage short-circuiting resistance section 522 in the generator separately excited field circuit. Thus the generator E. M. F. is further increased causing the motor to run at a faster speed. Also contacts E 725 engage completing the circuit for the actuating coil F 726 of the third accelerating switch. This circuit may be traced from terminal 595, by way of line 596 through contacts A 608, by way of line 597 through contacts E 725, resistance 728, reactance 730 and coil F 726, line 723, back to terminal 602 as traced for the coil T 716. As in the case of switch E, switch F is retarded in its operation by reactance 730. The reactances 722 and 730 thus provide a time element between the operation of the accelerating switches.

Switch F, upon operation, causes the separation of contacts F 600 and the engagement of contacts F 731. The separation of contacts

F 600 breaks one of the parallel circuits shunting elevator motor field resistance 529, the resistance remaining short-circuited however by contacts Z 598. The purpose of contacts F 600 will be seen from later description. Contacts F 731 short-circuit resistance section 523 in the generator separately excited field circuit again increasing the generator E. M. F. and the speed of the elevator motor.

The actuating coil Z 732 of the speed control switch is connected across the armature 696 of the elevator motor, the switch operating when the generator E. M. F. has built up to substantially full value to cause the separation of contacts Z 598 and Z 673 and the engagement of contacts Z 733. The purpose of contacts Z 673 and Z 733 will be explained later. The separation of contacts Z 598 removes the short-circuit for resistance 529 in the elevator motor field circuit bringing the elevator motor up to full speed.

It is to be noted that the down hall and car stop brushes 280 and 278 engage the first floor stationary contacts during upward movement of the car. No circuit is completed by their engagement however, even though the first floor stop contact 694 is "alive", because the circuit for the brushes is broken at down direction relay contacts Q 734. As contacts Q 734 remain separated during up motion of the car, the engagement of these brushes and the stationary contacts for the other floors is without effect. If neither the up second nor third floor hall button has been pushed, the engagement of the up hall stop brush 281 with the up second and third floor hall stop contacts 735 and 736 does not complete a circuit. However, upon the engagement of the up car stop brush 277 with the fourth floor car stop contact 544 as the car approaches the fourth floor, a circuit is completed for the reset coil 323 of the car button fourth floor switch. This circuit may be traced from alternating current main 502, line 547, by way of line 635 through contacts M 572 and resistance 642, line 737, by way of line 738 through contacts P 664, brush 277, contact 554, by way of line 740 through contacts 333, 346 and coil 323, line 552, line 553, to main 503. It is to be noted that a portion of this circuit beginning with line 737 establishes a shunt circuit for coil SS 574 of the stop switch. The increased current flow in line 635 up to line 737 raises the potential drop across resistance 642 and as a consequence decreases the voltage applied to coil SS 574 causing the stop switch to drop out. The energization of the reset coil 323 of the car button fourth floor switch causes the tripping of the latch for its forward contacts. As a result of this reset operation, forward contacts 333, 346 and 334, 347 separate and back contacts 375, 377 engage. The separation of contacts 333, 346 and the engagement of contacts 375, 377 are to prepare

120
115
125
130

the switch for further operation. The separation of contacts 334, 347 is without effect as the circuit for coils VV 822 and UU 555 is maintained by the car button first floor 5 switch contacts 334, 347.

The stop switch SS, upon dropping out, causes the engagement of contacts SS 636 and SS 578 and the separation of contacts SS 638 and SS 640. The separation of contacts SS 10 640 and the engagement of contacts SS 636 and SS 578 are in preparation for the next starting operation, it being noted that the circuit for coil DP 575 is broken at contacts H 577. The separation of contacts SS 15 638, however, breaks the circuit for the pawl magnet coil 241. Thus as the selector machine cross-head continues its movement, the up pawl 260 engages the up fourth floor stopping collar 261 causing the consecutive opening 20 of the "selector" switches 155, 156, 157 and 158. The opening of up "selector" first slow down switch 155 breaks the circuit for coil F 726. The third accelerating switch drops out immediately due to the fact that its 25 actuating coil discharges into a high resistance circuit comprising resistances 721, 728 and 741. Switch F, upon dropping out, causes the separation of contacts F 731 and the engagement of contacts F 600. The separation 30 of contacts F 731 reinserts resistance sections 523 and 525 in series with the generator field 508 to decrease the E. M. F. of the generator, contacts Z 673 being separated as previously explained. The engagement of 35 contacts F 600 short-circuits resistance 529 increasing the strength of the elevator motor field for the stopping operation. By providing contacts both on the speed control switch Z and on the third accelerating switch F for 40 short-circuiting resistance 529, in the starting operation the strength of the elevator motor field is not decreased until the generator E. M. F. has built up substantially to full value while in the stopping operation the 45 strength of the elevator motor field is increased immediately retarding is initiated. The generator E. M. F. being lowered and the strength of the elevator motor field being increased, the speed of the elevator motor 50 is lowered.

The opening of the up "selector" switch 155 also breaks the circuit for coil E 716 of the second accelerating switch. This switch, however, does not open immediately, its action 55 being delayed by the effect of the reactance 722 in series with its coil and the discharge resistance 741 in parallel with the reactance and its coil. Upon dropping out, switch E causes the separation of contacts E 725 in preparation for the next starting operation and of contacts E 724 reinserting 60 resistance section 522 in the circuit of the generator field 508. Thus the generator E. M. F. is again lowered and the speed of the elevator motor reduced.

The opening of the up "selector" second slow down switch 156 deenergizes the coil D 710 of the first accelerating switch and the coil T 711 of the leveling switch motor relay. The switch D, upon dropping out, causes the separation of contacts D 714 and D 713. The separation of contacts D 714 is in preparation for the next starting operation. The separation of contacts D 713 reinserts resistance section 520 in the circuit of the generator 70 field 508 further decreasing the E. M. F. of the generator and therefore the speed of the elevator motor. The resistance section 521 is not reinserted in the generator field circuit at this time due to the fact that contacts Z 733 are closed, the actuating coil Z 732 of the speed control switch acting to maintain the switch operated at a lower voltage than that applied to cause the operation of the switch. 75

The leveling switch motor relay T, upon dropping out, causes the separation of contacts T 717 to deenergize the leveling switch motor 535. In this manner the operating rollers of the leveling switch are extended 80 for engagement by the leveling cams. Referring briefly to the system for Elevator No. 1 in Figure 1, the leveling switch motor is operatively connected to the leveling switch by means of an arm 742 on the motor shaft, a connecting link 743 and a lever 744. In the starting operation, the motor 535 being energized, arm 742 rotates acting through link 743 and lever 744 to move the leveling switch as a whole about a pivot. In this 85 manner the leveling switch operating rollers 745 and 746 are moved into position where they do not engage the leveling cams 747 and 748 during motion of the car, a stop being provided to determine the extent of the 90 movement. The leveling switch is pivoted on a bracket 750 secured to the car frame. In the stopping operation, upon the deenergization of the leveling switch motor, a spring (not shown) moves the lever 744 and therefore the leveling switch back into the first 95 described position with the rollers 745 and 746 extended for engagement by the leveling cams. The leveling switch comprises up slow and fast speed pairs of contacts 751 and 752 100 respectively and down slow and fast speed pairs of contacts 753 and 754 respectively. Each pair of contacts comprises a stationary contact and a movable contact operated by engagement of its corresponding roller 105 and leveling cam. The fast speed contacts are arranged to separate before the slow speed contacts in the leveling operation. Springs (not shown) are provided for causing 110 the separation of the contacts of the pairs as the leveling operation is effected and stops are provided for determining the extent of movement of the rollers as they ride off the leveling cams. The opening of the up "selector" second slow down switch is so timed 115 120 125 130

- that the up leveling switch operating roller 745, upon the return movement, strikes against the vertical surface of the up leveling cam 747, causing the engagement of both the 5 up slow and fast speed contacts 751 and 752. Referring again to Figures 23 and 24, the up fast speed leveling contacts 752 complete the circuit for the fast speed leveling relay actuating coil LF 755. This circuit may be 10 traced from terminal 595, by way of line 596 through contacts A 608, by way of line 756 through coil LF 755 and leveling contacts 752, by way of line 601 through contacts A 610, to terminal 602. The fast speed leveling relay, 15 upon operation, causes the engagement of contacts LF 757 completing an additional short-circuit for resistance section 517, sections 517 and 518 being short-circuited by contacts R 670. The up slow speed leveling 20 contacts complete another circuit for the actuating coils H 625 and B 624 of the motor field switch and up direction switch respectively. This circuit may be traced from terminal 595, by way of line 596 through contacts A 608, by way of line 661 through gate contacts 546 and coils H 625 and B 624, by way of line 758 through leveling contacts 751 and up slow speed leveling relay actuating coil LU 760, by way of line 601 through contacts A 610, to terminal 602. By breaking the circuit for the coil T 711 by means of the up "selector" second slow down switch 156, the engagement of the slow speed leveling 30 contacts is effected before the up "selector" 35 stop switch 157 opens. Thus the up direction switch and motor field switch do not drop out when the up "selector" stop switch 157 opens, their actuating coils being maintained energized by leveling contacts 751 through the circuit above traced. By controlling the energization of coils H 625 and B 624 in this manner, a smooth stopping operation is assured. It is to be understood that the coil T 711 may be placed in series with either coil E 716 or 40 coil F 726, if desired, in order to render certain the engagement of the leveling contacts before "selector" switch 157 opens. It is to be noted that the up direction switch and motor field switch are maintained operated 45 so long as leveling contacts 751 are closed, regardless of the condition of the up direction relay, "selector" switches, "director switch", door contact relay and the contacts represented in this example by contacts UU 560. 50 Upon the separation of up "selector" door lock control switch 158, the circuit is broken for time relay coil W 648 and cam motor switch coil V 647. Relay W, upon dropping out, causes the engagement of its contacts W 633 completing the circuit for the motor 392 and clutch magnet coil 483 of the time switch. Switch V, upon dropping out, causes the separation of its contacts V 651 deenergizing the door lock cam motor 538. As will be seen 55 from Figure 1, the spring 703 acts to move the retiring cam 654 away from the car so as to cause its engagement with roller 655 with the car at the landing.
- As was seen from the above description, actuating coil LU 760 of the up slow speed leveling relay was energized upon the engagement of slow speed leveling contacts 751. This relay, upon operation, causes the engagement of contacts LU 761 completing the circuit for the up coil X 762 of the series field relay and the actuating coil R 763 of the slow down switch. This circuit may be traced from terminal 595, by way of line 596 through contacts A 608, by way of line 764 through contacts LU 761, coil X 762 and a portion 75 of a reactance 766, by way of line 767 through coil R 763, line 768, by way of line 601 through contacts A 610, to terminal 602. The operation of relay X and switch R is delayed due to the fact that the circuit for their coils is through the portion 765 of reactance 766. The value of this reactance portion is chosen, however, so that the time element is very small. The switch R, upon operation, causes the separation of contacts R 670 inserting resistance section 518 in the circuit of the generator field 508, the resistance section 517 remaining short-circuited by contacts LF 757. Thus the generator E. M. F. is lowered and the speed of the elevator motor is still further reduced. The relay X, upon operation, causes the engagement of contacts X 770, completing the circuit for the actuating coil Y 771 of the series field switch. This circuit may be traced from terminal 595, by way of line 596, through contacts A 608, by way of line 768 through contacts X 770 and coil Y 771, by way of line 601 through contacts A 610, to terminal 602. The switch Y, upon operation, causes the separation of contacts Y 698 breaking the short-circuit around a portion of the resistance 516 in parallel with the generator series field 511. The generator series field is so wound that, without the parallel resistance 516, it would have too great an effect for proper operation of the car. The desired compounding is obtained by employing the low resistance shunt. By increasing the amount of this shunting resistance when switch Y operates, the strength of the series field is increased for the leveling operation so as to aid in bringing the motor to a stop, as will be seen from later description. The short delay in the action of relay X, and therefore the switch Y, upon the initiation of the leveling operation, is desirable in order that the current in the generator armature, elevator motor armature circuit may adjust itself to such a value that proper series field strength during the leveling operation may be obtained.
- As the car nears the fourth floor landing, roller 745 rides off the vertical surface onto the oblique surface of cam 747. This results in the opening of up fast speed leveling 130

contacts 752 and the consequent deenergization of coil LF 763 of the fast speed leveling relay. This relay drops out separating contacts LF 757 to insert resistance section 517 in the circuit of the generator field 508. Thus the generator E. M. F. is again lowered and the motor runs at its lowest speed.

Shortly before the car reaches an exact level with the landing, the roller 745 rides off the oblique surface of cam 747 thereby separating the slow speed leveling contacts 751. The circuit for coils H 625, B 624 and LU 760 is thus broken. Switch H drops out causing the separation of contacts H 681, H 682 and H 683 and the engagement of contacts H 676, H 677 and H 577. The purpose of contacts H 681 will be seen from later description. The separation of contacts H 683 reinserts resistance 528 in series with the elevator motor field reducing the current therein to a "standing field" value. The separation of contacts H 682 breaks the circuit for the brake release coil 530 and coil O 702. The accelerating relay O drops out causing the separation of contacts O 708 and the engagement of contacts O 644 in preparation for the next starting operation. The engagement of contacts H 677 reinserts the low resistance 533 in parallel with the brake release coil 530 to "soften" the application of the brake. The engagement of contacts H 676 reconnects the generator field 508 to the generator armature. The polarity of this connection is such that the generator sends current through field 508 in such direction as to oppose the flux which produces the generator E. M. F., thus tending to destroy the residual flux of the generator field. The engagement of contacts H 577 completes the circuit for the actuating coil DP 575 of the dash pot relay. The dash pot relay, therefore, again starts its operation.

Up direction switch B, dropping out along with switch H, causes the separation of contacts B 662 and B 663 and the engagement of contacts B 666. The purpose of contacts B 666 will be seen from later description. The separation of contacts B 662 and B 663 disconnects the generator field from lines 596-601, the field being simultaneously connected to the generator armature by the engagement of contacts H 676 as explained above. Up slow speed leveling relay LU, dropping out along with switches B and H, causes the separation of contacts LU 761 de-energizing coil X 762 and coil R 763, the relay X and switch R dropping out in preparation for the next starting operation. It is to be noted that the circuit for coil Y 771 is broken by the separation of contacts X 762, the switch Y also dropping out in preparation for the next starting operation.

Thus, the brake being applied and the generator separately excited field disconnected from the exciter, the car is brought to rest

level with the fourth floor landing. It is to be noted that, as the brake is applied, the brake contacts 686 reengage, the reengagement being in preparation for the next starting operation. A sudden change in the strength of the generator field as each step of resistance is inserted in the stopping operation is prevented by the action of the discharge resistance 514 across the field winding.

In the event of an overrun, the operation of the switches is modified. Assuming in the above example that the car overruns the fourth floor to the extent of causing the engagement of down slow speed leveling contacts 753, a circuit is completed for coil H 80 625, coil C 773 of the down direction switch and coil LD 774 of the down slow speed leveling relay. This circuit may be traced from the terminal 595, by way of line 596 through contacts A 603, by way of line 661 through coils H 625, by way of line 775 through coil C 773, by way of line 776 through leveling contacts 753 and coil LD 774, by way of line 601 through contacts A 610, to terminal 602. Switch C operates to cause the engagement of contacts C 777 and C 778 connecting the generator field 508 to lines 596-601 for reverse operation. Switch H operates simultaneously with switch C to cause the disconnection of the generator field 508 from the generator armature, the disconnection of the resistance 533 from across the brake release coil 530, the energization of the brake release coil, and the strengthening of the elevator motor field. The relay LD operates simultaneously with switches H and C to cause the engagement of contacts LD 780, completing a circuit for the down coil X 781 of the series field relay, and for coil R 763 of the slow down switch. This circuit may be traced from terminal 595, by way of line 596 through contacts A 608, by way of line 782 through contacts LD 780, coil X 781 and portion 783 of reactance 766, by way of line 767 through coil R 763, line 768, to terminal 602 as previously traced. The brake being released and the generator field being energized, the elevator motor starts in the down direction to return the car to the floor. The relay X and switch R do not operate immediately. When contacts LU 761 closed upon approaching the floor, the current flowing through the reactance portion 765 caused a flux to be built up in reactance 766 in one direction. Upon the separation of contacts LU 761, the current in the reactance discharged into resistance 784 tending to maintain this flux built up. Upon closing contacts LD 780 on an overrun, the current supplied to coils X 781 and R 763 must reverse the flux in the reactance, thus taking a longer time to build up to a value sufficient to cause the operation of relay X and switch R. Contacts R 670, therefore, remain closed long enough to permit sufficient current to be supplied to the generator field 508 to cause the 130

- motor to start the car in the down direction, contacts R 670 short-circuiting resistance sections 517 and 518. Contacts Y 698 also remain closed temporarily in order to insure that the current in the generator armature, elevator motor armature circuit has fallen to a low value, the operation of switch Y depending on the operation of relay X as previously explained. Since the current in the series field may be flowing in a direction such as to cause the generation of an E. M. F. which is of proper polarity for operating the car in the reverse direction, immediate increase in strength of the series field might result in an overrun in the opposite direction. As the car returns to the floor, it is stopped by the separation of slow speed leveling contacts 753 in a manner similar to that described for approaching the floor.
- 20 If the overrun is great enough to cause the engagement of the down fast speed leveling contacts 754 as well as slow speed contacts 753, a circuit is completed for the fast speed leveling relay coil LF 755, as previously traced.
- 25 As previously described, the operation of relay LF causes the engagement of contacts LF 757. When switch R operates to separate contacts R 670, therefore, the resistance section 517 remains short-circuited by contacts LF 757 causing the elevator motor to run at its fast leveling speed. Further than this the operation on an overrun is as above described.

In order to obtain proper speed regulation for various load conditions, it is preferred to adjust the series field of the generator to give proper compounding for starting and stopping. The generator field resistance and elevator motor field resistance are then adjusted so that, upon engagement of contacts F 731 and separation of contacts F 600 and Z 598, the car runs at the desired speed for lowering a load, i. e., light load up or full load down. In order to obtain the desired speed when lifting a load, an additional step of resistance in the circuit of the generator field is short-circuited. The operation of cutting out the additional step of resistance may be effected by means of the load switch S. This switch is provided with a current coil S 701, previously referred to, and a voltage coil S 785 connected to the generator armature. These coils act cumulatively when the elevator motor is lifting a load and are adjusted to cause the operation of the switch at balanced load. Upon operation, contacts S 672 separate, for a purpose to be explained later, and contacts S 786 engage to short-circuit resistance section 526 bringing the elevator motor up to the desired speed.

During the starting operation the steps of resistance in the field circuit are so proportioned as to suit the requirements of the particular installation both as regards the time for bringing the car up to speed and the

smoothness of the starting operation. It has been found that the best results are obtained by making the first step of resistance large and successively decreasing the steps which follow. During retardation, however, in order to cause the car to slow down in a desired time interval, which may be less than the time interval during starting, it has been found that the first step of resistance cut in the circuit of generator field 508 should be large as compared with the last step of resistance cut out during the starting and that the last step of resistance cut in before the leveling operation should be correspondingly reduced so as to be small as compared with the first step of resistance cut out during starting. Such operation is obtained by means of the speed control switch Z.

As has already been explained, contacts Z 733 are separated and contacts Z 673 are in engagement during the starting operation. Thus the first step of resistance to be cut out comprises sections 520 and 521, the second step section 522 of less ohmic value, and the third step section 523 of still less ohmic value. In the stopping operation, however, contacts Z 673 are separated and contacts Z 733 are in engagement so that the first step of resistance to be cut in comprises sections 523 and 525, the second step section 522, and the third step section 520, the switch Z holding in during retardation is previously set forth. The load switch S, by means of its contacts S 672, assists in bringing the car to an accurate stop under different conditions of load, as may better be seen from examples.

With the car traveling up with light load, the elevator motor armature is supplying current to the generator armature and therefore the generator series field is opposing the separately excited field. The load switch S therefore is not operated, its contacts S 672 being in engagement and its contacts S 786 being separated. Thus, when contacts F 731 are separated, reinsertion of resistance sections 523 and 525 reduces the generator E. M. F. and therefore increases the regenerative braking action, slowing down the elevator motor. Similarly, reinsertion of resistance sections 522 and 520 by the separation of contacts E 724 and D 713 increases the regenerative braking action, further reducing the speed of the motor. The values of resistance sections 525 and 520 may be adjusted so that the desired retardation is obtained. Assume for comparison that the car is traveling up with full load which means that the generator is supplying current to the elevator motor and therefore that the generator series field is assisting the separately excited field. The load switch S, therefore, is operated and its contacts S 672 are separated. Thus when contacts F 731 are separated a large step of resistance is reinserted in the circuit of the generator field 508, the step comprising resist-

ance section 524 as well as sections 523 and 525. In this manner the tendency of the series field to keep the generator E. M. F. above the counter E. M. F. of the elevator motor is 5 overcome by a large reduction in the generator field strength so that regeneration is immediately effected. Immediately the motor starts to regenerate, the current in generator series field is reversed, the series field then 10 acting to assist in the retardation. It will be obvious that several load switches may be employed and so calibrated as to operate at different values of positive load.

With the car stopped at the fourth floor, 15 the retiring cam 654 is in engagement with the roller 655, causing the unlocking of the door and the separation of the fourth floor door contacts. Upon the separation of door contacts 542, the door contact relay coil I 657 is deenergized. Thus contacts I 658 and 20 I 660 are separated in preparation for the next starting operation. It is to be noted that separation of these contacts during the leveling operation is without effect as contacts I 658 are by-passed by the circuit including down slow speed leveling contacts 753 and contacts I 660 by the circuit including up slow speed leveling contacts 751. Thus the passenger may open the gate and door and 25 step from the car. The opening of the gate causes the separation of gate contacts 545 and 546. As the passenger's weight is removed from the car, the gate contacts are by-passed by the platform switches 543 and 544. As has 30 previously been explained, the door is re-closed automatically. The dash pot relay has been slowly operating after the completion of the circuit for its actuating coil DP 575 and after a certain time interval, for example 35 ten seconds as previously indicated, causes the engagement of its contacts DP 634. In the event of an overrun, contacts H 577 are separated, due to the engagement of the slow speed leveling contacts 578, permitting the 40 turn of the dash pot relay to deenergized position without causing the engagement of its contacts DP 634. The time interval starts, therefore, from the time that the car is actually stopped at the floor, thus allowing 45 ample time for the gate and door to be opened. The engagement of contacts DP 634 again completes the circuit for coil SS 574 of the stop switch. Thus with the platform switch 543 closed, a circuit is again completed for 50 the pawl magnet coil 241 through contacts UU 560 of the car button relay. Contacts UU 560 remain closed because the circuit for its actuating coil is maintained by forward contacts 334, 347 of the car button first floor switch. Thus the car starts in the up direction in the manner previously described, the platform switches 543 and 544 replacing the 55 gate contacts 545 and 546 respectively in the circuit traced.

60 65 If no up hall buttons are pushed, the car

proceeds to the tenth floor where it is stopped automatically. It is preferred to effect the stop at this landing by means of the "director switch" permitting the "selector" machine to serve as a check to insure the stopping operation. Thus as the car approaches the tenth floor landing, the roller on the "director switch" operating arm strikes the hatchway cam 87, gradually moving the segment 54 off contacts 47, 46, 43 and 50 in the order named. The car is thus slowed down and stopped in a manner similar to that described for the stop at the fourth floor, it being noted that contacts 47, 46 and 43 are connected to the "selector" switches 155, 156 70 and 157 respectively. The contour of the hatchway cam is such that the "director switch" is moved into "neutral" position just 75 before the tenth floor landing is reached.

The opening of the "selector" switches to insure the stopping operation is effected by the cam 305, carried by the crosshead, causing the opening of switch 300 as the car approaches the terminal landing. The opening of switch 300 breaks the circuit for the pawl magnet coil 241, resulting in the opening of the "selector" switches in the manner previously described. The switch 300 and cam 305 are so arranged that the switch is opened with the car at such a distance from the landing that the engagement of the pawl 260 and up tenth floor stopping collar 261 is assured. It is to be noted that neither contacts SS 638 of the stop switch nor contacts UU 560 of the car button relay are separated during this 80 operation. It is to be noted also that the up direction relay actuating coil P 612 is de-energized with the "director switch" in "neutral" position so that both contacts P 623 and down direction relay contacts Q 790 in 85 the pawl magnet coil circuit are separated.

With the car stopped at the terminal landing, both the up direction switch contacts B 666 and the down direction switch contacts C 791 are in engagement. Thus, as the reversing brush 282 is in engagement with the tenth floor reversing contact 312, a circuit is completed for the "director switch" motor 127. This circuit may be traced from terminal 595, by way of line 596 through contacts A 608, by way of line 792 (connecting Figures 23 and 24) through contacts B 666 and C 791, brush 282, contact 312, by way of line 793 through switch 105 and "director switch" motor down series field 794, "director switch" motor armature 795, line 796 (connecting Figures 24 and 23), by way of line 601 through contacts A 610, to terminal 602. The "director switch" motor operates in the 90 previously described manner to move the "director switch" from "neutral" into down position. As the "director switch" moves into down position it breaks the circuit for the motor 127 by opening switch 105.

Upon the "director switch" segment 54 en- 95

gaging the contact 42 in its movement, a circuit is completed for the actuating coil Q 797 of the down direction relay. This circuit may be traced from terminal 595, by way of line 596 through contacts A 608, by way of line 798 through coil Q 797, line 800, "director switch" contacts 42 and 48 bridged by segment 54, line 616, by way of line 618 to terminal 602 as previously traced. The 10 down direction relay operates to cause the engagement of contacts Q 734, Q 790 and Q 801. The engagement of contacts Q 734 prepares a circuit for the down brushes 280 and 278 rendering them "alive". The engagement of 15 contacts Q 801 prepares a circuit for coils C 773 and H 625. The engagement of contacts Q 790 completes the circuit for the pawl magnet coil 241, switch 301 having been closed as the car left the first floor during the first 20 described starting operation. Thus as the down "selector" door lock control switch 163 closes, the circuit for coils W 648 and V 647 is again completed. The switch V operates in the previously described manner to effect 25 the energization of the door lock cam motor 538, the motor acting in turn to effect the energization of door contact relay coil I 657. Thus upon the closure of contacts I 658, a circuit is completed for the coils H 625 and C 30 773. This circuit may be traced from terminal 595, by way of line 596 through contacts A 608, by way of line 661 through platform switch 544 and coil H 625, by way of line 775 through coil C 773, contacts I 658 35 and contacts Q 801, down "selector" stop switch 162, line 800 to terminal 602 as previously traced. The down direction switch C, upon operation, causes the separation of contacts C 791 in the circuit for the director 40 switch motor 127 and the engagement of contacts C 777 and C 778 completing the circuit for the generator separately excited field 508 for down car travel. Further than this it is believed that the operation of starting the 45 car in the down direction will be obvious from previous description, the "director switch" segment bridging contacts 48, 42, 44 and 45 and the "selector" switches 160 and 161 being closed. It is to be noted that, due to the fact that the stop switch SS remains 50 operated, there is no time element involved in the stop and reversal of direction of travel at the tenth floor.

If no hall buttons are pushed, the car proceeds to its home station, the first floor in the present example. As the car approaches the first floor, the "director switch" is moved into "neutral" position in the above described manner. At the same time, the engagement 55 of down car stop brush 278 and contact 694 completes a circuit for the reset coil 323 of the car button first floor switch. This circuit may be traced from alternating current main 502, line 547, by way of line 635 through contacts M 572 and resistance 642, line 737, 60 by way of line 804 through contacts Q 734, brush 278, contact 694, by way of line 805 through contacts 333, 346 and coil 323, line 552, line 553, to main 503. As in the case of the stop at the fourth floor, a portion of this 65 circuit beginning with line 737 establishes a shunt circuit for coil SS 574 of the stop switch. As a result of the reset operation forward contacts 333, 346 and 334, 347 separate and back contacts 375, 377 engage. As 70 differentiated from the stop described for the fourth floor, the separation of contacts 334, 347 breaks the circuit for the car button relay actuating coil UU 555. This relay, upon dropping out, separates contacts UU 560 and 75 UU 561. The separation of contacts UU 561 is without effect as the circuit for coil M 562 is maintained by maintaining relay contacts G 628 and time switch contacts 457, 463. The separation of contacts UU 560 also is without effect at this time as contacts H 681 are 80 in engagement.

The stop switch SS, upon dropping out, causes the engagement of contacts SS 636 and SS 578 and the separation of contacts SS 638 and SS 640, contacts SS 638 being in the circuit for the pawl magnet coil 241 as above described. Switch 301 also in the pawl magnet coil circuit is opened by cam 305 as the car approaches the bottom floor. The circuit for the actuating coil Q 797 of the down direction relay is broken as the "director switch" segment 54 moves off contact 42. The relay Q, therefore, drops out separating contacts Q 734, Q 790 and Q 801. 85

Contacts H 681 maintain the circuit for the actuating coils of the accelerating switches until broken by the "director switch" segment and the circuit for coils H 625 and C 773 until after the down slow speed leveling contacts 753 engage. With the car brought to a level with the first floor landing, switch H drops out. Thus contacts H 577 are caused to engage completing the 90 circuit for the dash pot relay coil DP 575. The dash pot relay, therefore, again starts its operation. Also with the car at the first floor landing, coils W 648 and V 647 are de-energized, switch V effecting the door unlocking operation in the previously described manner. Relay W, upon dropping out, causes the engagement of contacts W 633, again completing the circuit for the time switch motor 392 and clutch magnet coil 483. With both contacts B 666 and C 791 in engagement, reversing brush 282 being in engagement with the first floor reversing contact 806, a circuit is completed for the "director switch" motor 127. This circuit may be traced from terminal 595, by way of line 596 through contacts A 608, by way of line 792 through contacts B 666 and C 791, brush 282, contact 806, by way of line 807 through switch 106 (closed during the movement of the "director switch" at the tenth floor) and "director 95 switch" 125 at the tenth floor. 130

switch" motor up series field 808, armature 795, line 796, by way of line 601 through contacts A 610, to terminal 602. The motor 127 thus moves the "director switch" from "neutral" into up position, its circuit being broken by switch 106 as previously described.

Upon the engagement of contacts DP 634 of the dash pot relay, the circuit is again completed for coil SS 574 of the stop switch. 10 The engagement of stop switch contacts SS 638 is without effect at this time due to the fact that the circuit for the pawl magnet coil is broken at the contacts represented by contacts UU 560. The contacts W 633, therefore, remain closed and the motor 392 remains in operation.

If at the end of a four minute period no buttons are pushed, it being assumed again for purposes of description that the time 20 switch is set for four minutes, the time switch operates to separate contacts 457, 463 breaking the circuit for the driving motor starting relay coil M 562. This relay, upon dropping out, causes the separation of contacts M 568, 25 M 570, M 571 and M 572. The separation of contacts M 570 breaks the circuit for the dash, pot relay coil DP 575. The deenergization of coil DP 575 is in the interest of reducing power consumption. The separation of contacts M 572 breaks the circuit for the stop switch coil SS 574, it being noted that the separation of dash pot relay contacts DP 634 does not effect the deenergization of coil SS 574 because the stop switch has established its own maintaining circuit. The deenergization of coil SS 574 also is in the interest of reducing power consumption. The separation of contacts M 568 is without effect as the circuit for coil K 580 is broken at 30 contacts L 581. The separation of contacts M 571 deenergizes coil L 573 of the driving motor running switch. Switch L, upon dropping out, causes separation of power contacts L 586, L 587 and L 588, disconnecting the driving motor from the alternating current mains. Switch L also causes the separation of contacts L 590 breaking the circuit for maintaining relay coil G 591 and the engagement of contacts L 593 short-circuiting minimum current field relay coil J 35 594. The relay G, upon operation, causes the separation of contacts G 627 and contacts G 628. The separation of contacts G 628 is in preparation for the next starting operation, the circuit for coil M 562 having been broken by the time switch contacts 457, 463. The separation of contacts G 627 breaks the circuit for the motor 392 and clutch magnet coil 483 of the time switch. The time switch 40 contacts 457, 463, therefore, are again closed in the manner described in connection with Figures 19, 20 and 21. The closure of these contacts is without effect at this time as contacts G 628 are separated. Relay J, upon dropping out, causes the separation of con-

tacts J 603 breaking the circuit for the potential switch coil A 604. The potential switch contacts A 608 and A 610, upon separation, break the common lines 596 and 601 for the control circuits and generator field, preparing the system for the next starting operation. In this manner the standby losses of the motor generator set are reduced. This arrangement acts to stop the motor generator set if for any reason the car is stopped an unusually long time during regular service as well as to prevent the motor generator set from running all night. 75

For convenience of further description however, it will be assumed that a prospective passenger pushed the up fourth floor hall button 810 before the four minute period had elapsed. A circuit is thus completed for the closing coil 321 of the up hall button fourth floor switch. This circuit may be traced 80 from main 502, line 547, by way of line 811 through coil 321 and back contacts 375, 377, line 553, to main 503. This floor switch operates in the manner previously described to cause the engagement of its contacts 333, 346 85 and 334, 347 and the separation of its contacts 375, 377. The engagement of contacts 333, 346 prepares a circuit for the up fourth floor hall stop contact 812 rendering it "alive". The engagement of contacts 334, 347 completes a circuit for the actuating coils of the hall button relays, coil WW 812 being for Elevator No. 1 and coil ZZ 816 for Elevator No. 2. This circuit may be traced from alternating current main 502, line 547, line 100 813, by way of line 814 through contacts 334, 347 and resistance 815, back to line 813 through coil WW 812, and a portion of coil ZZ 816, the remaining portion of coil ZZ 816 being short-circuited by arm 817 of another 105 of the switches 385, and line 818, line 553, to main 503. Elevator No. 2 hall button relay ZZ does not operate at this time as insufficient current is supplied to the active portion of its actuating coil. Relay WW, however, operates to cause the engagement of contacts WW 820 and WW 821, the engagement of contacts WW 821 being without particular effect at this time as the circuit for relay coil M 562 is being maintained by contacts G 628 110 and contacts 457, 463. The engagement of contacts WW 820 prepares certain control circuits including the circuit for the pawl magnet coil 241 and completes the circuit for the up direction relay coil P 612 through the 115 platform switch 543. The engagement of up direction switch relay contacts P 623 completes the circuit for the pawl magnet coil. The system now operates in the previously described manner to cause the car to start in 120 the up direction. 125

During this starting operation, the home station relay contacts U 687 are again closed causing the operation of the car button first floor switch. As previously described, the 130

- engagement of the car button first floor switch contacts 333, 346 prepares a circuit for the stationary contact 694. The engagement of contacts 334, 347 completes a circuit for a portion of Elevator No. 1 service relay coil VV 822 and car button relay coil UU 555. It is believed that this circuit is obvious from the circuit previously traced for these coils, it being by way of line 827 through contacts 334, 347 and resistance 826. As in the previous example, relay VV does not operate. Relay UU operates, however, causing the engagement of contacts UU 561 and UU 560. The engagement of both contacts UU 561 and UU 560 is without particular effect at this time, contacts UU 561 by-passing contacts WW 821 and series arranged contacts G 628 and 457, 463 and contacts UU 560 by-passing contacts WW 820 and H 681.
- Assume that the up second floor hall button 830 and down third floor hall button 831 are pushed before the car arrives at its stopping distance from the second floor landing, i. e., before the up hall stop brush 281 engages up hall stop contact 735. The up hall button second floor switch, upon operation, causes the engagement of its contacts 333, 346 to prepare a circuit for contact 735, rendering it "alive", and causes the engagement of its contacts 334, 346 to establish an additional path for the current to coils WW 812 and ZZ 816 through resistance 832. The down hall button third floor switch, upon operation, causes the engagement of its contacts 333, 346 to prepare a circuit for down third floor hall stop contact 833, rendering it "alive" and causes the engagement of its contacts 334, 347 to establish through resistance 850 still another path for the current to coils WW 812 and ZZ 816. The current now supplied to coil ZZ 816 is still insufficient to cause the operation of Elevator No. 2 hall button relay ZZ. Upon the engagement of brush 281 and contact 735, a circuit is established for the up hall button second floor switch reset coil 323. This circuit may be traced from alternating current main 502, line 547, by way of line 635 through contacts M 572 and resistance 642, line 737, by way of line 738 through contacts P 664, brush 281, contact 735, line 834, bar USZ, by way of line 881, through contacts 333, 346, line 553, to main 503. It is to be noted that, as in the previously described examples, a portion of this circuit establishes a shunt circuit for coil SS 574 of the stop switch. The up hall button floor switch is thus reset causing the separation of its forward contacts. The circuit for the pawl magnet coil 241 is broken upon separation of stop switch contacts SS 638 causing the car to slow down and stop at the second floor.
- Assume now that the passenger has gotten in the car at the second floor. Upon the closure of gate contacts 545 and 546 and of contacts
- SS 638, the car is again started. Assume that the passenger desires to go to the fourth floor and pushes the fourth floor car button 551. The car button fourth floor switch is thus operated to render contact 554 "alive" and to establish an additional path through resistance 825 for the current supplied to coils VV 822 and UU 555.
- Upon the engagement of down hall stop brush 280 and third floor down hall stop contact 833, no circuit is completed, the brush 280 being "dead" because of the separation of down direction relay contacts Q 734. Upon the engagement of up car stop brush 277 and car stop contact 554 and of up hall stop brush 281 and up hall stop contact 812, circuits are completed for effecting the reset of the car button fourth floor switch and the hall button fourth floor switch respectively. Portions of both circuits shunt stop switch coil SS 574 as is obvious from previous description. The stop switch, therefore, drops out causing the car to slow down and stop at the fourth floor. The separation of car button fourth floor switch contacts 334, 347 is without particular effect as the circuit for coils VV 822 and UU 555 is maintained by contacts 334, 347 of the car button first floor switch. The separation of contacts 334, 347 of the hall button fourth floor switch also is without effect as the circuit for coils WW 812 and ZZ 816 is maintained by contacts 334, 347 of the down hall button third floor switch. Thus it will be seen from the description of the stop at the fourth floor that, when both the car button and hall button for the same floor have been pushed, both floor switches are reset preventing later false stops.
- Assume now that the passenger who has gotten on the car at the fourth floor wishes to go to the tenth floor. With the gate and door closed and stop switch contacts SS 638 in engagement, the car starts automatically, proceeding in the same direction, i. e., toward the up terminal landing. The passenger may push the tenth floor car button at any time before the car arrives at its stopping distance from the tenth floor landing since the forward contacts of the floor switch, once in engagement, are maintained so until tripped out by a reset operation. The slow down and stop at the tenth floor is accomplished in the manner previously described. In addition to these operations, however, upon the engagement of up car stop brush 277 and "live" tenth floor car stop contacts 835, the car button tenth floor switch is reset and a shunt circuit is established for stop switch coil SS 574. As the stop switch, upon dropping out, not only separates contacts SS 638 in the circuit for the pawl magnet coil but also contacts SS 640 breaking its own holding circuit, the car cannot be started again until the dash pot relay operates to reestablish the

circuit for the stop switch coil. Thus, when a tenth floor button has been pushed, sufficient time is allowed, after the car has stopped at the tenth floor landing, for the opening of 5 the gate and door.

The "director switch" is reversed at the tenth floor landing so that upon closure of the door and the engagement of stop switch contacts SS 638, the car is started in the down 10 direction. Assume that someone has pushed the down seventh floor hall button and then decides that he does not desire the use of the car. The down hall button seventh floor switch is reset, however, as the car approaches 15 the seventh floor and stop switch contacts SS 638 are separated causing the car to slow down and stop at the seventh floor landing. The car remains at the floor however for only a short period of time, determined by the adjustment of the dash pot relay. Upon the 20 engagement of dash pot relay contacts DP 634, the stop switch again operates to cause the engagement of contacts SS 638 completing the circuit for the pawl magnet coil 25 to start the car.

The car therefore proceeds to the third floor where, upon engagement of down hall stop brush 280 and down third floor hall stop contact 833, the down hall button third floor 30 switch is reset and the car is caused to slow down and stop in the manner previously described. The separation of contacts 334, 347 of the down hall button third floor switch breaks the circuit for coils WW 812 and 35 ZZ 816. Relay WW, upon dropping out, causes the separation of contacts WW 820 and WW 821. The separation of these contacts is without effect at this time as contacts WW 820 are by-passed by contacts 40 UU 560 and contacts WW 821 are by-passed by contacts UU 561 and by contacts G 628 and 457, 463 in series. Assume that the passenger who gets on the car at the third floor desires to go to the first floor. If he pushes 45 the first floor car button 693, nothing happens in response as the circuit for the closing coil 321 of the car button first floor switch is broken at back contacts 375, 377, the operation 50 of the car button first floor switch having been caused by the home station switch 386 and relay U as previously described. If in the meantime, other hall push buttons have been operated, the car does not remain at the home station after discharging the passenger 55 but proceeds in the up direction after the door has closed and contacts SS 638 have engaged.

It will be seen from the previous description that response is had to all buttons, regardless of the order in which they are pushed, since the contacts of the floor switches, once in engagement, are maintained so until tripped out by reset operations. Also it is believed clear that response is had 60 regardless of the time that the buttons are 65

pushed. If, for example, with the car traveling in the up direction, up hall stop brush 281 has passed up fourth floor hall stop contact 812, when the up fourth floor hall button 810 is pushed, the car proceeds again to the 70 fourth floor after the stop at the home station. As will be seen from later description however, another car may respond to the call at the fourth floor.

Referring now to the whole of Figure 24 as 75 well as Figure 23, the operation of a bank of elevators will be described. It will be understood that the alternating current power mains are common to all the elevators. The power and control circuits for the additional 80 elevators will not be shown since they are identical with those illustrated in Figure 23 for Elevator No. 1. As has previously been set forth, the hall button floor switches for the intermediate floors are arranged in pairs, 85 one hall button floor switch being provided for each terminal floor. These switches, along with their corresponding hall buttons, are common to all the elevators of a bank. The reset circuit for each of these switches 90 leads from an individual bus bar. These bars have been characterized generally in accordance with a floor and circuit. For example, DS 4 indicates that the bar is in the down fourth floor stop circuit. The bars are 95 common to all the elevators of a bank. Thus, as will be seen from later description, the pushing of a hall button not only renders the corresponding hall stop contacts of Selector machine No. 1 "alive", but also the corresponding hall stop contacts of Selector machine No. 2. Each elevator car is provided with a set of car buttons, the sets operating independently. 100

It is believed that unnecessary duplication 105 will be avoided and that the invention will be clear from the illustration of the circuits for the selector machines for two elevators. It is to be understood, however, that the operation of any number of elevators in a 110 group is contemplated. The selector machine wiring diagram for Elevator No. 2 is identical with the selector machine wiring diagram for Elevator No. 1 and will not be described in detail except as set forth in the description 115 of operation. The designating letters employed for the various switches, such as SS for the stop switch and P for the up direction relay, are used for both selector machine diagrams, differentiation being had by changing the added reference numerals. The wiring diagrams for the two selector machines are arranged for both cars at rest at the first floor with the "director switches" 120 in up position, the "director switch" for Elevator No. 2 not being shown. It will be assumed that the home station for each car is at the first floor.

Assume now that the up fourth floor hall button 810 has been pushed. Up hall button 125

fourth floor switch contacts 333, 346 and 334, 347 are therefore in engagement. Due to the engagement of contacts 333, 346, circuits are prepared for Selector machine No. 5 1 up fourth floor stop contact 812 and for Selector machine No. 2 up fourth floor stop contact 840, rendering them "alive". Due to the engagement of contacts 334, 347, a circuit is completed for coils WW 812 and 10 ZZ 816 through resistance 815. Elevator No. 1 hall button relay WW operates to cause the engagement of contacts WW 820 causing Car No. 1 to start in the up direction. As previously indicated, the current supplied to 15 the active portion of coil ZZ 816 is insufficient to cause the operation of this relay. As in the previous examples, upon the starting of the car, the operation of Elevator No. 1 car button first floor switch is effected by the 20 home station relay.

Assume further that before Car No. 1 arrives at its stopping distance from the fourth floor landing three or more additional hall buttons are pushed, for example the down 25 fourth, third and second floor hall buttons 841, 831 and 842 respectively. The corresponding floor switches operate, therefore, to cause the engagement of their contacts 333, 346 and 334, 347. The engagement of down 30 hall button fourth floor switch contacts 333, 346 prepares circuits for Selector machine No. 1 down fourth floor stop contact 843 and for Selector machine No. 2 down fourth floor stop contact 844, rendering them "alive". In 35 a similar manner Selector machine No. 1 down third and second floor stop contacts 833 and 845 respectively and Selector machine No. 2 down third and second floor stop contacts 846 and 847 respectively are rendered "alive" by contacts 333, 346 on the down 40 hall button third and second floor switches. The engagement of down hall button fourth, third and second floor switch contacts 334, 347 establishes additional paths for the current 45 for coils WW 812 and ZZ 816 through resistances 848, 850 and 851. Due to the fact that four resistances are now arranged in parallel in the circuit for these coils, sufficient current is supplied to the active portion of coil ZZ 816 50 to cause the operation of Elevator No. 2 hall button relay ZZ. The contacts on relay ZZ are arranged in the control circuits for Elevator No. 2 in the same relation as contacts WW 820 and WW 821 in the control circuits 55 for Elevator No. 1. Thus Car No. 2 is caused to start in the up direction. As has previously been described for Elevator No. 1, the home station relay U for Elevator No. 2 operates during the starting of Car No. 2 60 to cause the engagement of contacts U 852. A circuit is thus completed for Elevator No. 2 car button first floor switch closing coil 321 which circuit may be traced from main 502, line 547, line 548, line 853, by way of line 854 65 through contacts U 852, Elevator No. 2 home station switch arm 855 and first floor contact 856, line 857 (thus by-passing Elevator No. 2 first floor car button 858), coil 321, contacts 375, 377, line 860, line 553, to main 503. This floor switch operates in the previously described manner to render Elevator No. 2 first floor car stop contact 861 "alive" and to complete a circuit for Elevator No. 2 car button relay actuating coil XX 862. This circuit may be traced from main 502, line 547, line 548, line 853, line 863, by way of line 864 70 through contacts 334, 346 and resistance 865, back to line 863 through switch arm 817 of one of the switches 385 for Elevator No. 2 and line 866 (arm 817 and line 866 short-circuiting Elevator No. 2 service relay actuating coil YY 867), coil XX 862, line 553, to main 503. The contacts of relay XX correspond with contacts UU 560 and UU 561 and are arranged in the same relation in the control 75 circuits for Elevator No. 2 as contacts UU 560 and UU 561 are arranged in the control circuits for Elevator No. 1.

Upon the engagement of up hall stop brush 281 and contact 812 of Selector machine No. 1, the up hall button fourth floor switch is reset and Car No. 1 is caused to slow down and stop at the fourth floor. As up hall button fourth floor switch contacts 333, 346 separate, up hall stop contact 840 of Selector machine 80 No. 2 is rendered "dead" and Car No. 2, therefore, continues past the fourth floor. If none of the remaining up hall buttons are pushed, Car No. 2 proceeds to the tenth floor where it is slowed down and stopped and where, upon the reversal of its "director switch", it is caused to start in the down direction. It is to be noted that Elevator No. 2 down direction relay contacts Q 868 are caused to engage upon the movement of Elevator No. 2 "direction switch" into down position. Thus, assuming that Car No. 2 is now ahead of Car No. 1, upon the engagement of Selector machine No. 2 down hall stop brush 870 and fourth floor contact 844, a circuit is completed for reset coil 323 of the down hall button fourth floor switch. This circuit may be traced from main 502, line 547, line 548, line 853, by way of line 871 through Elevator No. 2 driving motor starting relay 85 contacts M 872, resistance 873 (contacts SS 874 being separated), line 875, by way of line 876 through contacts Q 868, brush 870, contact 844, line 877, bar DS 4, by way of line 878 through contacts 333, 346 and coil 323, line 553, to main 503. As described for Elevator No. 1, a portion of this circuit beginning with line 875 establishes a shunt circuit for Elevator No. 2 stop switch actuating coil SS 880, causing the stop switch to drop out. Car No. 2, therefore, is caused to slow down and stop at the fourth floor. It is to be noted that the reset of the down hall button fourth floor switch renders the down hall stop contacts of both selector machines "dead" so 100

105 110 115 120 125 130

that Car No. 1 is not caused to stop at the fourth floor upon its return to the home station.

Coil ZZ 816 may be so adjusted that it will 5 not maintain the relay operated when only two parallel resistances remain in circuit, i. e., when all but two hall buttons have been responded to. Car No. 2, however, continues in operation until the home station is reached 10 due to the fact that its car button first floor switch is operated. Furthermore, it is to be noted that the dropping out of relay ZZ does not affect Selector machine No. 2 hall stop contacts 846 and 847, these contacts remaining 15 "alive" until response is had to the down third and second floor hall buttons. As to whether Car No. 1 or Car No. 2 stops at the third and second floors depends upon which car is first to arrive at its stopping distance 20 from the respective landings. Thus, should Selector machine No. 1 down hall stop brush 280 engage hall stop contact 833 before Selector machine No. 2 down hall stop brush 870 engages hall stop contact 846, contact 846 is 25 rendered "dead" and Car No. 2 does not stop at the second floor. However, Selector machine No. 2 down hall stop brush 870 may engage hall stop contact 847 before Selector machine No. 1 down hall stop brush 280 enga- 30 ges contact 845, in which event contact 845 is rendered "dead" and only car No. 2 stops at the second floor. Thus, as regards calls from the floors with a plurality of cars running in the same direction, a stop is made only by 35 the car first to arrive at its stopping distance from the landing at which the call was registered.

Assume further in the above example that the up second floor hall button 830 also was 40 pushed but too late for Car No. 1 to respond. Selector machine No. 2 up hall stop contact 882, as well as Selector machine No. 1 contact 735 is rendered "alive". Car No. 2, upon starting up, responds to this call, completing 45 the reset circuit for the up hall button second floor switch through up direction relay contacts P 884 by the engagement of brush 883 and contact 882. As in the previous examples, a shunt circuit around stop 50 switch coil SS 880 is established upon the engagement of brush 883 and contact 882, the stop switch dropping out to cause Car No. 2 to slow down and stop at the second floor landing. Thus it will be seen that response is 55 always had to a hall button. In fact, this second floor call would be responded to by Car No. 1 on its next up run if the service is not heavy enough to cause the starting of Car No. 2. It is to be understood that the dash pot 60 relay of Elevator No. 2 acts in the same manner as that for Elevator No. 1. It is to be further understood that Car No. 2 responds to its car buttons in the same manner as de- 65 scribed for Car No. 1.

Car No. 2 is caused to stop at its home sta-

tion, the first floor, after completing its run in the same manner as described for Car No. 1. Elevator No. 2 time switch may be set to operate in two minutes so that, if the service is "light" for the next two minutes, Elevator 70 No. 2 motor generator set is automatically shut down.

Assume now that there are four passengers in Car No. 1 and that each desires to get off the car at a different floor, for example, the 75 second, third, fourth and tenth. The pushing of car buttons 885, 551, 886 and 887 causes Selector machine No. 1 car stop contacts 835, 554, 888 and 890 respectively to be rendered 80 "alive" and causes the completion of a circuit for coils VV 822 and UU 555 through four parallel resistances 891, 825, 892 and 893. Also upon the closing of the car button first floor switch upon the operation of the home station relay U, a fifth resistance 826 is added 85 in parallel to those above enumerated. It may be assumed that, with arm 817 of switch 385 for coil VV 822 in position b, sufficient current is supplied to the active portion of coil VV 822 to cause the operation of Elevator 90 No. 1 service relay VV. Relay VV, upon operation, causes the engagement of contacts VV 894 completing a circuit for coils WW 912 and ZZ 816 through resistance 895. As relay UU has already operated, the operation 95 of relay WW is without effect. The current supplied to the active portion of coil ZZ 816 is insufficient to cause the operation of relay ZZ. If no hall buttons are pushed, Car No. 100 1 operates in the previously described manner to discharge its passengers and return to its home station. Assume, however, that two of the hall buttons have been pushed, for example, the up buttons for the seventh and the eighth floors. Thus two resistances, corresponding 105 with resistances 848, 815, 850, 851 and 832, are connected in parallel with resistance 895. It is preferred to make resistance 895 of such ohmic value that the addition of two hall button resistances increases the current sufficiently to cause the operation of Elevator No. 2 hall button relay ZZ. Therefore, whenever Car No. 1 is required to make a predetermined number of stops in response 110 to the pushing of its car buttons, Car No. 2 is automatically started in response to the operation of a less number of hall buttons than required when less than the predetermined number of Car No. 1 car buttons are operated. Thus it will be seen that in a plural elevator 115 system arranged in accordance with the invention, one elevator car may be employed to bear the brunt of the service with the others automatically coming to its aid when the demand for service reaches a predetermined 120 point.

Due to the fact that the two elevator control systems are identical, Car No. 2 may be caused to bear the brunt of the service permitting Car No. 1 to serve as an aid. This may 125 130

- be accomplished by setting the switches 385 and the time switches. Thus to cause Car No. 2 to respond in the same manner as has been described for Car No. 1 and to cause 5 Car No. 1 to act in the same capacity as described for Car No. 2, switch 385 for coil VV 822 is set in position "a", switch 385 for coil YY 867 is set in position "b", switch 385 for coil W 812 is set in position "a" and switch 10 385 for coil ZZ 816 is set in position "d". Thus coil VV 822 is short-circuited as was coil YY 867; coil YY 867 has an active portion of turns equal to those which were active for coil VV 822; the active turns of coil WW 15 812 are reduced to correspond to those which were active for coil ZZ 816; and none of the turns of coil ZZ 816 are short-circuited corresponding with the previous condition of coil WW 812. The time switch for Elevator 20 No. 2 is set for four minutes and that for Elevator No. 1 for two minutes. It is believed obvious that, with the switches so arranged, the operation of the two cars is reversed. It is to be noted that the contacts YY 896 for 25 Elevator No. 2 service relay are arranged in series with resistance 897 in the circuit for coils WW 812 and ZZ 816.
- It is to be understood that the proportions assumed in the above examples are simply 30 arbitrary and chosen merely to illustrate the principles involved. Thus, for example, the system might be arranged so that relay ZZ in position "a" would not respond until after five or six hall buttons had been pushed 35 or so that relay ZZ would respond after three hall buttons had been pushed. Similarly, for example, the system might be arranged so that relay VV in position "b" would not respond until after six resistances 40 are included in parallel in its circuit, or, on the other hand, so that relay VV would respond when three resistances are so included. Further, for example, the value of resistance 45 895 might be changed so that relay ZZ would not respond until after three resistances are added in parallel to resistance 895 or, on the other hand, so that relay Z would respond as soon as one resistance was added. Also the 50 operation of the system may be changed by altering the position of the switches 385. Thus, for example, switch 385 for coil ZZ 816, can be moved to position "b" whereupon relay ZZ will respond after three hall buttons are pushed.
- If more than two elevators are arranged 55 in a bank, the number of hall button relays in line 813 will correspond with the number of cars in the bank and the number of service relays in each car button relay line, for 60 example line 556 of Elevator No. 1, will be one less than the number of cars in the bank. The number of active turns of the various coils will then be set in accordance with the requirements of the particular installation.
- The home station for each car may be va- 65
- ried by means of the corresponding home station switch 386. With the system installed in an apartment house for example, it would be desirable to have the home station for both cars at the first floor in the evening when the 70 majority of people are arriving at the apartment. In the morning, however, it would be preferable to have the home station for both cars at the tenth floor since the flow of traffic is from the upper floors to the street floor. 75 This is accomplished by moving the home station switches 386 to positions where arm 690 engages contact 898 and arm 855 engages contact 900. Obviously any floor may be made the home station for either car by mov- 80 ing the home station switch arm for that car into engagement with the contact corresponding with the floor. It is believed obvious from previous description that, if the home station for Car No. 1 is at the tenth floor, 85 with no first floor buttons pushed, the time element at the first floor, due to the dash pot relay DP, is eliminated. If desired, each system may be arranged so that the car re- 90 mains at the floor at which it was last stopped in the event that no other push buttons have been operated. This may be accomplished by moving the home station switch 386 for that car to "off" position. Thus the circuit including the contacts of the home station 95 relay U is broken so that the operation of this relay is without effect. With the home station switch moved to "off" position or to a position to cause the home station to be at some intermediate floor, the time element upon a stop 100 and reversal at each terminal landing is eliminated. Should a push button for either terminal landing have been operated, however, the car is caused to remain at that landing for a predetermined period before start- 105 ing in the opposite direction as previously described.
- In the event of an emergency, the direction of travel of Car No. 1, for example, may be reversed at any floor by means of the "di- 110 rector switch" motor switch 901 in the car. This switch has two operative positions and when moved counter-clockwise from its central position (as viewed in Figure 24) causes the operation of the motor 127 to move the 115 "director switch" from up into down position. If the "director switch" is already in down position, this operation is without effect as switch 105 is open. When this switch is moved clockwise, the operation of the mo- 120 tor 127 is effected in a similar manner to move the "director switch" into up position.
- Safety switch 607 is provided for stopping the car in case of an emergency. The opening of this switch breaks the circuit for coil 125 A 604, permitting the potential switch to drop out. Contacts A 608 and A 610 thus separate breaking the circuit for the generator shunt field and the control circuits, contacts H 682 separating to deenergize the 130

brake release coil 530. Contacts A 611 also separate disconnecting the parallel resistances 532 and 533 from across the brake release coil causing a "hard" application of the brake. It is to be noted that if the car is stopped at any point by the opening of the safety switch, its direction of travel may be reversed at that point by means of the "director switch" motor switch 901. Upon re-closing the safety switch the car is automatically started in the reverse direction. The opening of any of the "safety switches" included in line 605 or of switch 498 or of contacts J 603 effects the stopping of the car in the same manner.

In case of a dangerous overload on the generator, the protective relay N, due to the fact that its coil N 700 is in the generator armature, motor armature circuit, operates to separate contacts N 564. The relay N is preferably of the inverse time overload type. The coil M 562 of the driving motor starting relay is thus deenergized causing the separation of its contacts. As a result of the separation of contacts M 571 the driving motor running switch L is deenergized, the switch dropping out to cause the disconnection of the driving motor from the alternating current mains and to cause the short-circuiting of coil J 594 of the minimum current field relay. Contacts J 603 are thus separated causing the car to stop in the same manner as described for opening the safety switch 607.

35 In accordance with the provisions of the patent statutes, the principle of operation of the invention, together with the apparatus now considered to represent the best embodiment thereof, have been described; but it is desired to have it understood that the apparatus shown is only illustrative, and that the invention can be carried out by other means.

What is claimed is:

1. An electric elevator system comprising, 45 a motor, a generator for supplying current to said motor at a variable voltage, a field winding for said generator, a source of current for said winding, a resistance in circuit with said winding, means for short-circuiting the resistance in predetermined steps during acceleration of said motor, and means for increasing the amount of resistance in the last step, after it is short-circuited during acceleration, for reinsertion during retardation of said motor.

2. An electric elevator system comprising, a motor, a generator for supplying current to said motor at a variable voltage, a field winding for said generator, a source of current for said winding, a resistance in circuit with said winding, means for short-circuiting the resistance in predetermined steps during acceleration of said motor, and means for decreasing the amount of resistance in the first step, after it is short-circuited dur-

ing acceleration, and for increasing the amount of resistance in the last step, after it is short-circuited during acceleration, for reinsertion during retardation of said motor.

3. An electric elevator system comprising, 70 a hoisting motor, a generator for supplying current to said motor at a variable voltage, a field winding for said generator, a resistance in circuit with said winding arranged in steps, a plurality of accelerating switches 75 for successively short-circuiting certain of said steps during the acceleration of said motor, and an additional switch for short-circuiting another of said steps, said additional switch having two operating coils, one subject to the voltage across the motor armature and the other subject to the current supplied thereto and arranged to assist said one coil when the motor is lifting a load, said coils causing the operation of said additional 85 switch to short-circuit said other resistance step during acceleration upon increase of their combined magnetizing forces to a certain value.

4. An electric elevator system comprising, 90 a motor, a generator permanently connected to said motor for supplying current thereto, a driving motor for said generator, a source of current for said driving motor, means for connecting said driving motor to said source, 95 and an inverse time overload relay dependent on the current supplied by said generator to the first named motor for controlling said connecting means.

5. An electric elevator system comprising, 100 a hoisting motor, a generator for supplying current to said motor, a field winding for said generator, a source of current for said field winding, resistance in circuit with said field winding, and means for varying said resistance in steps during acceleration and retardation of the motor in such manner that the first step of resistance cut in the circuit of said winding during retardation is larger than the last step of resistance cut out of the 110 circuit of said winding during acceleration and that a later step of resistance cut in the circuit of said winding during retardation is smaller than the corresponding step of resistance cut out of the circuit of said winding 115 during acceleration.

6. An electric elevator system comprising, 120 a hoisting motor, a generator for supplying current to said motor at a variable voltage, a field winding for said generator, a source 125 of current for said winding, resistance in circuit with said winding for controlling the amount of current supplied thereto from said source, accelerating switches arranged to operate in sequence during acceleration of the motor to short-circuit steps of said resistance, said accelerating switches being further arranged to drop out in reverse sequence during retardation of the motor, and means for causing the amount of said resistance re- 130

- included in circuit with said winding in certain of said steps during retardation of the motor to be different from the amount of resistance in said certain steps which was short-circuited during acceleration of the motor. 5
7. An electric elevator system comprising, a hoisting motor, a generator for supplying current to said motor at a variable voltage, a field winding for said generator, a source of current for said winding, resistance in circuit with said winding for controlling the amount of current supplied thereto from said source, accelerating switches arranged to operate in sequence during acceleration of the motor to 10 short-circuit steps of said resistance, said accelerating switches being further arranged to drop out in reverse sequence during retardation of the motor, and means dependent on the voltage across the motor armature for 15 causing the amount of said resistance re-included in circuit with said winding in one of said steps to be different from the amount of resistance in said step which was short-circuited during acceleration of the motor. 20
- 25 8. An electric elevator system comprising, a hoisting motor, a generator for supplying current to said motor at a variable voltage, a field winding for said generator, a source of current for said winding, resistance in circuit with said winding for controlling the amount of current supplied thereto from said source, accelerating switches arranged to operate in sequence during acceleration of the motor to 30 short-circuit steps of said resistance, said accelerating switches being further arranged to drop out in reverse sequence during retardation of the motor, and means dependent on the voltage across the motor armature for 35 causing the amount of said resistance re-included in circuit with said winding in one of said steps during retardation of said motor to be greater than the amount of said resistance in said one step which was short-circuited during acceleration of said motor and 40 for causing the amount of said resistance re-included in circuit with said winding in another of said steps during retardation of said motor to be less than the amount of said re- 45 sistance in said other step which was short-circuited during acceleration of said motor. 50
9. An electric elevator system comprising, a hoisting motor, a generator for supplying current to said motor at a variable voltage, a field winding for said generator, a source of current for said winding, resistance in circuit with said winding for controlling the amount of current supplied thereto from said source, accelerating switches arranged to operate in sequence during acceleration of the motor to 55 short-circuit steps of said resistance, said accelerating switches being further arranged to drop out in reverse sequence during retardation of the motor, and means dependent on the current supplied to the motor armature for 60 causing the amount of said resistance re-included in circuit with said winding in one of said steps to be different from the amount of resistance in said step which was short-circuited during acceleration of the motor. 65
10. An electric elevator system comprising, a hoisting motor, a generator for supplying current to said motor at a variable voltage, a field winding for said generator, a source of current for said winding, resistance in circuit with said winding for controlling the 70 amount of current supplied thereto from said source, accelerating switches arranged to operate in sequence during acceleration of the motor to short-circuit steps of said resistance, said accelerating switches being further arranged to drop out in reverse sequence during retardation of the motor, and means dependent on the voltage across the motor armature and the current supplied thereto for 75 causing the amount of said resistance re-included in circuit with said winding in one of said steps during retardation of said motor to be different from the amount of resistance in said step which was short-circuited during acceleration of the motor. 80
